John F. Donan, Reseda, Ralph R. Powell, Los Angeles, and Chris A. Christoff, San Gabriel, Calif., assignors to Clazy Corporation, San Gabriel, Calif., a corporation of California

Filed July 16, 1957, Ser. No. 672,851
15 Claims. (Cl. 235—159)

This invention relates to calculating apparatus and has particular reference to relatively high speed electronic calculating apparatus.

The principal object of the present invention is to provide a calculating apparatus of the above type capable of performing the four cardinal types of calculations and various combinations thereof.

Another object is to provide an electronic calculating apparatus having a maximum degree of flexibility of control.

Another object is to provide an electronic calculating apparatus embodying a novel form of adding and subtracting circuit.

Another object is to provide an electronic calculating apparatus utilizing a preset decimal point wherein the decimal point may be preset in different positions.

Another object is to provide an electronic calculating apparatus in which values registered by a multi-denominational register may be printed by a printer having a smaller capacity than the register.

Another object is to provide a key controlled electronic calculating apparatus in which errors due to partial key depression are eliminated.

Another object is to provide an electronic calculating apparatus incorporating a minimum number of components.

Another object is to provide an electronic calculating apparatus wherein the last number registered may be recalled as a factor for a new calculation.

Another object is to provide an electronic calculating apparatus having a plurality of registers wherein a value registered by any of said registers may be transferred for use as a factor in a succeeding calculation.

Another object is to provide an electronic calculating apparatus having provision for automatically accumulating factors or results of a series of calculations.

Another object is to provide a novel form of programming unit for an electronic calculating apparatus.

Another object is to provide a readily interchangeable and inexpensive program control unit for an electronic calculating apparatus.

The manner in which the above and other objects of the invention are accomplished will be readily understood on reference to the following specification when read in conjunction with the accompanying drawings, wherein:

FIG. 1 is a plan view of a keyboard embodied in a preferred form of the present invention.

FIG. 2 is a schematic block diagram illustrating the magnetic drum and circuits generally associated therewith.

FIG. 3 is a schematic view illustrating the various drum channels in developed form.

FIG. 4 is an expanded developed view illustrating one word section.

FIG. 5 is a graph of an exemplary wave form recorded on the drum and illustrating the amount 87 recorded thereon.

FIG. 6 is a schematic view illustrating the various sync patterns obtained directly from the drum and from the sync flip-flops S1 and S2 shown in FIG. 12.

FIG. 7 is a circuit diagram illustrating in detail cir-

2

cuitry the S1 flip-flop, the latter being typical of all flip-flops.

FIG. 8 is a graph of the wave shapes at different parts in the circuit of the flip-flop S1.

FIG. 9 is a block diagram of the pulse counter comprising flip-flops B1 and B2 together with logical equations depicting the terms required to trigger the inputs for each flip-flop.

FIG. 10 is a table indicating the different states of the pulse counter when counting the different identified pulses.

FIG. 11 is a circuit diagram of the logical net directly associated with the pulse counter.

FIG. 12 is a block diagram of the sync flip-flops S1 and S2 along with the logical equations for triggering the S2 flip-flop.

FIGS. 13 and 14 are circuit diagrams of the logical net associated with the sync flip-flops S1 and S2 and the pulse counter flip-flops B1 and B2.

FIG. 15 is a schematic view illustrating the various operational states through which the computer may pass in performing different operations.

FIG. 16 is a block diagram of the program counter flip-flops N1 to N6 together with the logical equations for triggering these flip-flops.

FIG. 17 is a table indicating the different possible states of the program counter.

FIG. 18 is a logical product for the inputs to the N flip-flops.

FIG. 18A is a logical product gate for generating the term PnC used to control the N flip-flops.

FIG. 19 illustrates the diode nets for partially generating the computer state terms.

FIGS. 20, 21 and 22 illustrate further diode nets for completing generation of the computer state terms.

FIGS. 23 to 26 illustrate diode nets for generating circuit logical sums and products mainly from the outputs of the program counter flip-flops to be used as input terms in other diode nets or flip-flop inputs in the machine logic.

FIG. 80 is a front view of a prewired program plug adapted to be plugged in the socket unit of FIG. 79.

FIGS. 81 and 82 are views of a stepper switch.

KEYBOARD

Amounts are entered into the machine by a keyboard which is also effective to predetermine and initiate functioning of the machine. Referring to FIG. 1, the keyboard comprises a number of keys, each operatively connected to a switch for controlling the machine circuitry. Certain of the keys effect operation of the machine upon depression thereof and these are shown crosshatched.

The keys are mainly arranged in four groups, indicated by dot-dash outlines 11, 12, 13 and 14, for convenience in control.

Amounts forming factors of problems to be solved by the machine are entered serially, digit by digit, through ten amount keys, located in group 11, in a manner similar to that generally followed in manipulating ten key adding or calculating machines. A back space key 15 is effective, upon each depression, to back space an amount entered into the machine through the amount keys by one decimal digit. A correction key 16 enables cancelling of any amount entered through the amount keys and before a calculating operation has been initiated.

The group 12 comprises the main operation control keys. Included in this group are plus key 17, minus key 18, total-product key 20, first factor or multiplicand key 21, second factor or multiplier key 22, subtotal key 23 and print-only key 24.

The latter keys, when depressed by themselves, cause the machine to operate in a normally expected manner. That is, for example, to add two amounts, one such amount is entered in the amount keyboard and the plus key 17 depressed. Then, the second amount is entered and the add key again depressed. Thereafter, a total may be obtained in printed form by depressing the total-product key 20.

Multiplication is performed by entering the first factor in the amount keys and depressing the first factor key 21. Thereafter, the second factor is entered and the second factor key 22 is depressed. The product is then obtained in printed form by depressing the total-product key 20.

The result of any arithmetic operation performed by the machine is generally registered in a so called working accumulator or register which actually comprises a certain section of the magnetic drum. It is from this accumulator that a result of a calculation, i.e., a total or product, is obtained and printed upon depression of the total key 20. Likewise, depression of the subtotal key 23 will effect a subtotaling out of the working accumulator.

The keys in group 14 control accumulator selection and operation. Ten storage accumulators or registers are provided in certain sections of one channel on the magnetic drum, each accumulator having a correspondingly identified accumulator selection key A1 to A10 located in this group. Such keys are settable in depressed positions and released as an incident to a machine operation or by depression of a release key 25.

Any storage accumulator may be cleared and the amount registered thereby printed by first setting the appropriate accumulator key in depressed position and then depressing a "clear A" key 26. A settable "reset A" key 27 is settable to enable resetting of an amount from any selected storage accumulator as any of a number of different factors. That is, an amount registered in any storage accumulator can be set up as a first factor, a second factor, augend, addend, minuend, divisor, or dividend by first depressing the selected accumulator selection key, the reset A key, and then the appropriate motor operation key. For example, if it is desired to reset an amount registered in storage accumulator No. 3 as a first factor, the accumulator key A3 and the reset A key 27 are first set and thereafter the key 21 is depressed, thereby setting

such amount in the machine in lieu of having to reenter the same through the keyboard in the usual manner.

An "enter minus" key 35 causes the contents of the working accumulator to be entered subtractively into any selected storage accumulator. Also, an "enter plus" key 36 likewise causes the contents of the working accumulator to be entered additively into any selected storage accumulator.

The keys in group 13 are provided mainly to control division operations and their function is believed to be self-evident. Suffice it to say that the dividend key 30 is depressed to enter a dividend amount either directly from a storage device for the ten key amount section, or from a selected storage accumulator, or from the working accumulator (in the event that the keys 20 and 30 are simultaneously depressed). The divisor key 31 effects entry of a divisor amount from either the amount keyboard storage device, a selected storage accumulator or the working accumulator, and also initiates the division operation.

The quotient key 32 enables printing of the quotient from the quotient accumulator. Such result, however, may be reentered as a first factor, second factor, addend, augend or minuend by depressing the key 32 simultaneously with the appropriate motor operation key. The remainder key 33 enables any remainder in a division operation to be printed.

The last amount entered into the keyboard may be recalled at any time and utilized as a desired factor by merely depressing appropriate factor entry keys, i.e., 17, 18, 21, 22, 30, 31, 35 and 36.

A settable switch lever 38, when set from its illustrated position to a second position, enables the contents of the working accumulator obtained in response to depression of key 20 to be accumulated automatically in storage accumulator No. 1. A second settable switch lever 40, when set from its illustrated position to a second position, causes all second factors entered in response to depression of the key 22 to be automatically accumulated in the storage accumulator No. 2 as long as a second settable switch 41 is in its normal illustrated position.

A settable switch lever 39, when set from its illustrated position to another, disables the printing mechanism.

The settable switch lever 41, when set to an abnormal position, causes all products obtained upon depression of the key 20 to be invariably entered into accumulator No. 2 (if switch lever 40 is in its second condition) and also into selected ones of accumulators Nos. 3 to 10.

An additional lever 42, when set in one position, enables any number printed which may result in an amount greater than the capacity of a format switch controlling the printer, to be printed on successive lines of print.

A memory clear key 45, when depressed, causes clearance of all amounts registered anywhere in the machine.

A counter reset switch 44 is provided, which when depressed resets the program counter to an initial position.

GENERAL DRUM AND CIRCUIT ARRANGEMENT

Referring particularly to FIG. 2, the computer comprises, in general, an electronic logic circuitry, generally indicated at 100, and comprising various keyboard operated switches, relays and flip-flops which either independently or in combination, through diode nets, transfer information in the form of pulses onto and from a magnetic drum 101. The latter is constantly rotated at a uniform speed and forms a timing device for the apparatus and a storage for the different factors and results. The drum also stores intermediate information being processed during a calculation.

The drum may be of well-known construction, preferably being formed of non-ferrous material such as aluminum, having an iron oxide coating thereon, in which information is recorded in the form of magnetized spots in coded form along the track or channel arranged around the periphery of the drum.

The drum has four channels thereon associated with

certain read and record heads for transferring information in the form of electrical pulses to and from the channels. An "A" channel or line is provided (FIG. 2) and is associated with a read head, generally indicated by the open arrow 102, and a record head, generally indicated by the two filled arrows 103.

The A line is divided mainly into sixteen word sections as indicated in the developed view at the top of FIG. 3. The different word sections are allocated for storage of different types of information, such as quotient, remainder, first storage, dividend, etc. Each word section is divided into twenty digit sections, as seen in FIG. 4, for the storage of a maximum of twenty decimal digits in coded form. Each digit section is divided into four bit or pulse sections for recording in binary coded decimal form, any of the digits from 9 to 0. For example, the digit 4 is recorded as 0100 and the digit 7 is recorded as 0111.

Although information may be retained permanently in the A line, it is generally erased, especially in certain word sections, during each calculation operation and new information recorded by the record head 103.

It should be noted that pulses are recorded in the A line in accordance with the well-known "non-return to zero" system in which the magnetic flux induced by the drum surface to record an amount is reversed only when going from a 1 to 0 condition or vice-versa and is retained in whatever condition it is set through any number of bit or pulse times until a pulse is received indicative of a change, as from 0 to 1. Thus, for example, the magnetic flux registering an amount eighty-seven in two adjacent digit sections of the drum will, through read head 102 and amplifier and pulse shaping circuits 105, develop a wave form illustrated at (a) in FIG. 5. Such wave form will be passed to a bi-stable read flip-flop A5, the operation of which will become clear from a detailed description later on. Accordingly, one of the output lines A5 of the flip-flop will register the wave form shown at (b) in FIG. 5.

Information is transferred to the record head 103 from the machine logic through two record flip-flops AR1 and AR2, one output of each thereof being connected through suitable driver circuits 106 to the windings of the record head 103.

It will be noted that the heads 102 and 103 are spaced one hundred fifty-eight bit sections apart. However, due to the particular operation of the flip-flops, as will be described later, each flip-flop will in effect delay the transmission of digit information therethrough by one pulse time. Accordingly, if information were to be recirculated in line A, such line would be effectively lengthened by two additional pulse times, one for the read flip-flop and one for the record flip-flop. Thus, the read and record heads for the A line may be considered to be spaced apart one hundred and sixty pulses or two word times.

In view of the above system of recording the A line, no erasing means need be provided since any newly recorded information will completely blanket any previously recorded information passing under the recording head.

A clock channel is provided to control the basic timing of the machine and is associated only with the read head 107. The clock channel has a number of pulses permanently recorded thereon, one for each bit section on the A line. The clock pulses derived from the clock channel are fed through an amplifier 110 and are utilized particularly to synchronize operation of all flip-flops and to actuate various flip-flop counting circuit arrangements.

A permanently recorded synchronizing or sync channel 109 is also provided to locate each word section on the A line and to control the main timing of the machine. This is associated with a single read head 108.

The output of the read head 108 for the sync channel is fed through amplifiers 110, the outputs of which are

fed over separate lines to two inputs $s1$ and $os1$ of a read flip-flop S1.

The fourth or recirculating channel contains three separate recirculating lines, i.e., the E line, F line and G line. These lines are of the volatile or dynamic type, i.e. information recorded thereon is always erased after being read.

The E line has a read head 111, a record head 112 and a permanent magnet erase head 113 associated therewith and located just ahead of the record head. Likewise, the F line has a read head 114, a record head 115 and a permanent magnet erase head 116 associated therewith. The G line has a read head 117, a record head 118 and a permanent magnet erase head 120 associated therewith.

It will be noted on reference to FIGS. 2 and 3, that the read and record heads of the E line are spaced seventy-eight bits or pulse sections apart. Now, the read head 111 is connected through amplifiers 121 to the inputs of a read flip-flop E5 whose outputs are connected to the machine logic 100. On the other hand, information transmitted to the record head 112 for this line is transferred from the logic, through a record flip-flop ER and a driver circuit 122. Since in a recirculating connection wherein the output of flip-flop E5 is in effect connected to the record flip-flop ER, a delay of two pulses is involved, the effective length of the E line is considered to be eighty pulses or one word time. This is generally true when transferring from one line to another since in any case both a record and read flip-flop is involved. Thus, during recirculation of information in the E line, such information will be delayed one word time relative to information contained in the A line.

Considering the F line, the read and record heads 114 and 115, respectively, of this line are spaced seventy-four bit sections apart. The read head 114 is connected through amplifiers 1122 to the inputs of a read flip-flop F1, the outputs of which are connected to the machine logic through lines F1 and F1'. The input to the record head 115 is transferred from the logic through a record flip-flop FR and a driver circuit.

In certain recirculation operations, the output of F1 is in effect at times transferred to the input of FR without the interposition of other flip-flops. Under such conditions the effective spacing in time between the heads amounts to seventy-six pulse times or nineteen digits. Thus, under such circumstances and during rotation of the drum, the F line will recirculate, but will in effect back space one digit per word section relative to the E line. This same effect will take place when transferring from the A line or from the F line to the E line.

Four additional flip-flops F2 to F5, inclusive, are provided. These are similar to F1 and are located in cascaded relation with each other. At certain times, these additional flip-flops are connected in cascade relation to F1 through the logic 100. When such connection is effected, and bearing in mind that each flip-flop will delay the transmission of information by one pulse time, the effective spacing in time between the heads 114 and 115 will then be exactly twenty digits or one word.

The read and record heads of the G line are likewise spaced seventy-four bit sections apart. Here, also, the read head 117 is connected through an amplifier circuit to the input of a read flip-flop G1 which is normally cascaded with four additional flip-flops G2 to G5, inclusive. Likewise, information from the logic is transmitted through a record flip-flop GR and a driver circuit to the record head 118. Accordingly, when the information read by head 117 is transferred through all flip-flops G1 to G5 and then recorded by head 118, the spacing between the heads will be, in effect, twenty digits or one exact word. However, if the output of G1 is

connected directly to the logic, the effective length in time between the heads will be nineteen digits.

As will become more apparent later on, information can be transferred from any of the memory lines A, E, F and G to any other through the machine logic. Also, such information which is either registered in or transferred to either of the F and G lines may be shifted forward one digit at a time by bypassing the associated group of cascaded flip-flops F2 to F5 or G2 to G5. Likewise, information may be shifted backward one digit at a time by transferring the information through four additional flip-flops.

FLIP-FLOP CIRCUITS

The general logic involved in the present apparatus physically utilizes the combination of diode nets and flip-flops as developed by methods of symbolic logic.

Propositions of logic are represented by proposition flip-flops as well as by keyboard and relay switches. Considering the flip-flops, when a proposition is "true," a corresponding flip-flop is set in one of its two bi-stable states which will be termed "true," and when the proposition is "false," the flip-flop is set in its opposite "false" state. Likewise, in the case of switches, when a proposition is true, a corresponding switch is located in one position which will be termed "true," and when false is located in an opposite "false" position.

Each flip-flop has two inputs and two outputs. The flip-flop is triggered to its true state by applying a relatively high positive potential or pulse to one input line, and is triggered to its false state by applying a high potential or pulse to the second input line. Also, both the true and false states of a proposition flip-flop are sensed as a relatively high positive voltage. Thus, the true state of the flip-flop is represented by a high voltage on one output line, and the false state by a high voltage on the other output line.

For the purpose of more readily understanding the disclosure, combinations of underlined capital letters and numbers are used for designating the flip-flops themselves. The outputs of the flip-flops are characterized by corresponding capital letters and numbers. Since one of the outputs corresponds to the flip-flop logic proposition being true and the other corresponds to the proposition being false, the false output is characterized by a prime and the true output is indicated by the absence of such prime.

The inputs to each flip-flop are designated by corresponding lower case letters and numbers. The input for rendering a flip-flop false is characterized by a zero preceding the lower case letter and the input for rendering the same true is characterized by the absence of such zero.

Describing now the construction and operation of the flip-flops, reference is made to FIGS. 7 and 8. The circuit shown in FIG. 7 is typical of all flip-flops and hence the details of one only, the S1 flip-flop, will be described. The flip-flop circuit comprises two PNP type transistors 125 and 126 and two grounded emitter NPN type drive transistors 127 and 128.

The emitters of transistors 125 and 126 are connected together and to a plus 4 volt supply through resistor R1. The collector of transistor 125 is connected through a bias resistor R2 and shunting capacitor C2 to the base of transistor 128. Likewise, the collector of transistor 126 is similarly connected to the base of transistor 127. The input s1 of the flip-flop is connected through an "and" gate 149 to the base of transistor 125 through a capacitor C3 which, with resistor R3, differentiates pulses transmitted by gate 149.

The gate 149, which is typical of other "and" gates throughout the apparatus, includes, in this case, two inputs 130 and 131 in addition to input s1. These inputs are connected through crystal diodes 132, 133 and 134, respectively, to the condenser C3. A resistor R4 is connected between the upper ends or anodes of the diodes and a source of relatively high potential to normally

block transmission of pulses through the gate. It is only when high positive potentials are concurrently applied to all three inputs that a high positive potential, generally in the form of a positive pulse, will be transmitted to capacitor C3.

The input 131 forms a cross connection to insure proper operation of the flip-flop and is connected at point 137 to the false output S1'. Thus, assuming the flip-flop to be in a false state, the output S1' will be high and the gate input 131 will be likewise maintained at high potential as indicated at (b) in FIG. 8.

The clock pulses indicated graphically at (a) in FIG. 8 are regularly applied to the gate input 130 from a clock pulse amplifier 1109 (FIG. 2). The amplifier 1109 includes suitable pulse shaping circuits therein to produce a clock pulse (as shown in FIG. 8a). Thus, upon application of a positive pulse 12 to input s1 (as indicated at (c) in FIG. 8) coincidentally with application of a clock pulse, the term s1 is considered to pass through the gate. The resulting gated pulse 138, indicated at (d) in FIG. 8, is of substantially the same shape as the current clock pulse and arrives coincidentally with it. The pulse 138 is differentiated by C3, R3 and is applied to the base of the transistor 125 in the form shown at (e).

In accordance with the well-known principle of operation of transistors, the positive spike of the differentiated wave form, will have no effect on the transistor 125, the latter at this time being assumed to be in cut-off condition. However, the negative spike 140, i.e., the differentiated falling edge of the pulse 138, causes the transistor 125 to act as a closed switch between its emitter and collector to apply positive potential from the plus 4 volt supply, over capacitor C2 to the base of transistor 128 and over capacitor C4 to the base of transistor 126. Here, the rise in potential will cause the transistor 128, which is assumed to be in cut-off condition, to complete a circuit from ground to point 137, thus lowering the potential of output S1'. Simultaneously, the positive pulse derived from transistor 125 will be applied through coupling capacitor C4 to the base of transistor 126 thereby cutting off the latter. Accordingly, minus potential will be applied from a minus 4 volt supply 141, through resistor R5 and capacitor C5 to the base of driver transistor 127. The latter will assume a cut-off condition and a relatively high voltage from a plus 30 volt supply 142 will be applied through resistor R6 to the output S1, rendering the same high (true) as indicated at (f) in FIG. 8. This output, however, is clamped at plus 10 volts by a diode 144 connected to a plus 10 volt source. Simultaneously, the negative potential from 141 will be applied to the base of transistor 125 to hold the same in a conducting condition.

The flip-flop will remain in its true state until application of a pulse to input os1 coincident with reception of a clock pulse.

It will be noted that the circuit elements for rendering the flip-flop false are similar to those just described for rendering it true. That is, the input os1 is controlled by a three input "and" gate 145, having one input for clock pulses, one for os1 and a third for a cross connection 146 from the S1 output.

As will become more apparent later on, the inputs to the proposition flip-flops can be represented by logical algebra equations. For the sake of convenience in understanding the disclosure, the equations for the proposition flip-flops are indicated below the schematic block diagrams thereof in the different figures.

Taking the equation which represents the input to a given proposition flip-flop to make it true, for example, the various terms representing the true or false states of the governing propositions are related either by logical multiplication or logical summation operations. By the use of logical diode nets to be described, these equations are solved. The solution is represented by a relatively high voltage level on a single wire. By connecting this

wire to the proper input of the flip-flop, the validity of the proposition is automatically determined by the state of the flip-flop.

It should be noted at this time that since the triggering action of the flip-flop occurs only during the trailing portion of a clock pulse or during the application of a negative spike 140 to the triggering transistor, i.e. 125, the output S1 will not be effective to trigger a second flip-flop controlled thereby until reception of the next successive clock pulse.

Flip-flop S1 is shown in simplified form in FIG. 12 along with the two logical product gates 145 and 149 which enable the flip-flop to be timed by means of the clock pulses C. The cross connections 131 and 146 between the flip-flop outputs and the third input of each gate are indicated. Also, since all flip-flops are of similar construction, the form shown in FIG. 12 is used to illustrate all other flip-flops.

TIMING AND SYNC CONTROLS

The sync track has permanently recorded thereon pulse representations effective to generate pulses indicated on line (b) in FIG. 6. These pulses are regularly spaced in sixteen groups corresponding to the sixteen different word sections and positions around the drum. The portions of several of such word groups are shown in FIG. 6. Certain unique pulses are, however, superimposed on the regular pattern of sync pulses at three locations to locate specific points on the drum. These unique pulses are termed P0 Sync, P1 Sync and P2 Sync.

The sync pulses in conjunction with individual pulse count pulses generated by a pulse counter comprising flip-flops B1 and B2, FIG. 9, control the timing of the flip-flops and other operating parts of the machine. The pulse counter is controlled by the magnetic spots recorded on the clock channel.

It should be noted at this time that the various pulse sections or bits of each digit of each word are designated P0, P1, P2 and P3 in the order named (see also FIG. 4). Also, the first digit of each word and word section on the drum is designated Y and the remainder, including the remaining nineteen digits, is designated Y'. In addition, the last pulse of each word section is designated Pn.

As previously noted in connection with FIG. 2, the sync track, through its read head 108, directly controls the flip-flop S1, causing its "true" output S1 to produce the wave shape shown in line (a) FIG. 6, and its "false" output S1' to produce a duplicate but inverted wave shape (not shown). This output S1, however, with the exception of the composite unique sync patterns defining the sync marks P0 Sync, P1 Sync and P2 Sync, rises at the beginning of a P3 pulse time and falls at the beginning of the succeeding P3 pulse time, one pulse time ahead of the beginning and end, respectively, of the corresponding Y portion of each word.

As will appear hereinafter, the pulse counter (FIG. 9) will operate in synchronism with the drum, being clocked by the clock pulses obtained from the clock channel to successively, through a logical net shown in FIG. 13, render pulse outputs P0, P1, P2 and P3 high in potential as the drum passes through such pulse positions and as it goes from one digit section to the next.

The flip-flop S2 (FIG. 12) is controlled by the logical product relation of the output S1 of flip-flop S1 and the P3 pulse time as determined by the pulse counter and net of FIG. 13 through a logical product "and" gate 150 (FIG. 14).

The gate 150, which is typical of all logical product "and" gates illustrated in this disclosure, comprises two input diodes 150a and 150b having their upper ends connected at junction 150c to the lower end of a load resistor R8 whose upper end is connected to a source of relatively high positive potential. Normally, when either or both of the inputs P3 and S1 are relatively low in po-

tential, the junction 150c and consequently s_2 is kept relatively low in potential. However, when both inputs are relatively high in potential, the output s_2 is rendered relatively high.

Accordingly, when the input P_3 is high in potential and the input S_1 is high in potential, the term $P_3 S_1$ is considered to pass through the gate 150, rendering the output s_2 high to set the flip-flop S_2 to its true state wherein its output S_2 is rendered high. This relation is indicated by the logical equation $s_2 = P_3 S_1 C$ noted below the block diagram of flip-flop S_2 .

Accordingly, the unique sync pulses P_0 Sync, P_1 Sync and P_2 Sync will not be manifested in the output S_2 . On the other hand, the input os_2 is controlled directly by the output S_1' of flip-flop S_1 as indicated by the logical equation $os_2 = S_1'$. Therefore, since, as noted heretofore, a flip-flop will act one pulse time later than a flip-flop which directly controls the same, the output S_2' will rise in potential, i.e. the output S_2 will fall, at the beginning of P_0 time, one pulse later than the drop in potential of S_1 . Thus, S_2 will directly define the Y portion of each word, as noted on line (c) FIG. 6.

Describing now the pulse counter (FIG. 9) and its associated logical nets of FIGS. 11 and 13, particularly, it will be noted that the logical equations located below the block diagrams of the flip-flops B_1 and B_2 indicate how the inputs of the flip-flops are controlled.

FIG. 10 indicates the various states through which the flip-flops B_1 and B_2 successively pass through in registering the various pulse times, P_0 , P_1 , P_2 and P_3 listed at the left of the column.

The "1" state of the flip-flop represents its true state wherein its right hand output is high and its left hand output is low. The "0" state of the flip-flop represents its false state wherein its left hand output is high and its right hand output is low.

It should be noted that the counter does not proceed through its various successive states in a normal binary fashion to count the four different pulse times, but counts in a predetermined manner and for a definite purpose as will be described later on.

It should also be noted that to better understand the action of the flip-flops, the connections of the outputs of the various flip-flops considered to control the right input of a certain flip-flop, i.e. the input which when triggered will make the certain flip-flop true, are determined by examining the states of all the flip-flops whenever the certain flip-flop is to change from false to true or from 0 to 1. The connections of the outputs of the various flip-flops considered to control the left input of the certain flip-flop, i.e., the input which renders the flip-flop false, are determined by examining the states of all the flip-flops whenever the certain flip-flop is to change from true to false or 1 to 0.

The coincidence of these flip-flop states are represented as logical products made up of the terms representing the flip-flop outputs.

As an example (and referring to FIGS. 9 and 10) when the flip-flop B_1 is to change from 0 to 1 on the occurrence of the next clock pulse, it must be currently registering 0, i.e., its output B_1' must be high. Therefore, the logical equation is simply $b_1 = B_1' C$. Likewise, a sufficient condition ordinarily necessary to change the flip-flop B_1 from 1 to 0 would be that it currently registers 1. However, in order to obtain isochronism as well as synchronism between the counter and the drum when starting the machine, an additional controlling or inhibiting term $S_1 + S_2'$ is added to the logical product equation resulting in $ob_1 = B_1(S_1 + S_2')C$. That is, referring back to FIG. 6, it will be noted that, on reference to lines (a) and (c), when the flip-flops S_1 and S_2 are in their condition $S_1' + S_2$, the pulse counter should be registering P_3 , i.e. $B_1 = 0$, $B_2 = 1$. By thus considering the term $(S_1 S_2)'$ as an inhibiting or controlling term and revising

it according to De Morgan's theorem by changing signs and primes $(S_1 S_2)' = (S_1' + S_2)$. This latter term is applied to the logical equation to prevent the counter from advancing at condition $S_1 S_2$. This possibly will re-5 occur until eventually $S_1 S_2$ is coincident with P_3 . From here on the counter is immune to the $S_1 S_2$ inhibit term and will count normally.

Describing now the logical net associated with the pulse counter B_1 , B_2 , reference is made in particular to FIGS. 10 9 and 11. It will be recalled from FIG. 7, that cross 10 connections are provided for the flip-flop circuits, connecting each true output with the false input of the same flip-flop and connecting the false output with the true input of such flip-flop. Such cross connections are shown at 150 15 and 161 in FIG. 9. These circuits, as well as the circuit carrying the term C representing the clock pulses, are, therefore, omitted from the details of the logical net for the sake of clarity.

Therefore, considering the equation $b_2 = B_1 B_2' C$, the 20 terms $B_2' C$ are taken care of in the flip-flop circuit itself, leaving only the term B_1 to be supplied. Accordingly, B_1 is directly connected to b_2 and is, therefore, also, not shown in the net.

The equation $b_1 = B_1' C$ is likewise taken care of in the 25 circuit of flip-flop B_1 itself.

Considering the equation $ob_1 = B_1(S_1 + S_2') C$, the terms B_1 and C are taken care of in the circuit of flip-flop 30 B_1 . The terms $S_1 + S_2'$ are obtained in a logical sum gate 152. Here the potential S_1 , as obtained from the 35 right hand output of S_1 , and S_2' , as obtained from the left hand output of S_2 , are fed into a pair of diodes having their cathodes connected at junction 153 to the upper end of a load resistor R_7 , the lower end of which is connected to a source 153 of relatively low or negative potential. Thus, whenever a high potential is applied to either of inputs S_1 or S_2' , a high potential will be applied to ob_1 to flip B_1 to a false state.

The output ob_2 of the net in FIG. 11 is found to be 40 the logical product of the terms $S_1 + S_2'$ multiplied by B_1 . Thus, in order to save components, the output of gate circuit 152 is cascaded into one of the inputs of a logical product gate 154 similar in circuitry to the gate circuit 150 of FIG. 14.

It should be noted, that all logical sum gates shown in 45 the various diode nets will be depicted in a manner similar to that of gate 152 and all logical product gates will be depicted in a manner similar to that of gate 154. However, such sum or product gates may have more than two inputs.

FIG. 13 illustrates the logical network for obtaining 50 the solutions for the pulses P_0 , P_1 , P_2 and P_3 , as well as for the sync pulses P_0 Sync, P_1 Sync and P_2 Sync, and the last word pulse or P_n for each word.

Here the solution for obtaining a P_0 Sync pulse is obtained at the output of a logical product gate 156 having two inputs. The left hand input is derived from the output of a product gate 157 having two inputs B_1 and B_2 (refer to FIG. 10). The right hand input of gate 156 is connected to a line 159 connected to the output of a product gate 158 having two inputs S_1 and S_2' . Accordingly, a P_0 Sync pulse, as graphically indicated on line 60 (e) of FIG. 6, is obtained only when inputs S_1 , S_2' , B_1 and B_2 are all high. This will occur at only one point in the rotation of the drum. The output P_0 , however, of gate 157 will be rendered high to form a P_0 pulse once every four pulses, and at the beginning of each digit of a word, when both B_1 and B_2 are high.

It will be seen that the diode nets for effecting the 70 solutions for terms P_1 Sync, P_2 Sync and P_n are similar to the nets for solving the P_0 Sync term. However, in the case of the P_1 Sync pulse, the output P_1 Sync will be rendered high only when the inputs B_1' , B_2' , S_1 and S_2' are all high. This will occur at only one point in the rotation of the drum and as indicated on line (f) in FIG. 75

6. The output P_2 Sync will be rendered high to form the P_2 Sync pulse only when inputs B_1 , B_2' , S_1 and S_2' are high, and this will occur as indicated on line (g) of FIG. 6. Likewise, the output P_n will be rendered high to produce the P_n pulse when inputs B_1' , B_2 , S_1 and S_2' are high. This will occur as indicated on line (d) in FIG. 6. Such pulse will occur at the end of each word time or sixteen times during the rotation of the drum.

The pulses P_0 , P_1 , P_2 and P_3 will occur in regular sequence as the pulse counter passes through its four 10 previously identified states B_1 B_2 , B_1' B_2' , B_1 B_2' and B_1' B_2 , respectively.

STATE PROGRAM COUNTER

In performing different arithmetic and other operations, the computer is advanced through certain operational states depending upon the particular operation being performed. Such states are depicted in block form in FIG. 15. Although there are sixty-two possible states through which the computer may pass, it never passes through all of such states in any one operation. Such states are consecutively numbered and identified according to the binary-octal number system. Thus, the states are numbered consecutively from #1 to #7, #10 to #17, #20 to #27, #30 to #37, #40 to #47, #50 to #56, #60 to #67 and #70 to #77.

During its operation, the machine may advance from one state to the next consecutive state upon completion of a word time or it may remain in the same state for two or more word times, or it may skip from one state to either a particular higher or lower numbered state depending upon certain control functions.

The particular manner in which the machine may be advanced through its different states is indicated by the flow lines in FIG. 15. For example, when the machine is in its normal rest state #4, it may either advance to the next higher state #5, as indicated by flow line 162, or it may remain or recirculate in its current state #4, as indicated by the flow line 163. Likewise, when the machine is in state #6, it may either advance to state #7 or it may return to state #3.

In general, and as will be brought out in more detail later on, the machine will progress through a certain group of states in performing a certain process. For example, states #12 to #24 comprise the print routine, states #60 to #71 comprise the multiply routine, states #73 to #2 comprise the divide routine, etc.

The machine is advanced through its several states by a state program counter comprising six program counter flip-flops N_1 to N_6 (FIG. 16) whose outputs are connected to appropriate diode nets (FIG. 19). The combined terms which are passed by these nets are applied to additional appropriate diode nets, shown in FIGS. 20 to 22, and their logical products solved by the latter nets identify the different states. These products enter into the control of the machine, as will be seen, and also partially control advancement of the counter.

A master flip-flop M (FIG. 27) normally controls the counter to remain in any state in which it is in or to advance or skip ahead or backward to a certain other state.

The logical nets for controlling the inputs to the N flip-flops are shown in FIG. 18.

FIG. 17 illustrates an octal table showing the various states of the N flip-flops when registering the different 65 computer states, the flow lines to the right of the table, indicating, as in FIG. 15, the manner in which the machine may skip to the different states or "stick" in one state. In general, the logical equations for the inputs to the N flip-flops are shown in FIG. 16.

In order to best understand the operation of the program counter in detail, the diode nets for solving the outputs for such flip-flops will be first described. Referring to the table in FIG. 17 and considering, for example, the 75

"rest" state #4, the program counter in this state registers 001 000, i.e. flip-flop N_3 is in a true condition and the remaining flip-flops are in false conditions. Accordingly, their outputs register $N_1'N_2'N_3$ $N_4'N_5'N_6'$. The terms $N_1'N_2'N_3$ are passed by a logical product gate 165 (FIG. 19) and the terms $N_4'N_5'N_6'$ are passed by a second product gate 166. The logical product of these two partial products $N_1'N_2'N_3$ and $N_4'N_5'N_6'$ is solved in a product gate 167 (FIG. 20) to produce the state identification term 4.

Similarly, for example, when the computer is in state #32, the counter will register, according to the table in FIG. 17, 010 110, i.e., the N flip-flops will register $N_1'N_2N_3'N_4N_5N_6'$. By referring to FIG. 19, the terms $N_1'N_2N_3'$ are passed by gate 168 and the terms $N_4N_5N_6'$ are passed by gate 170. By studying the program counter state gates in FIG. 20 to 22, it will be found that the gate 171 (FIG. 21) will pass the above partial products to define the state term 32.

The various other states may be found to likewise be solved by combination of certain of the partial product gates in FIG. 19 and certain of the product gates of FIGS. 20 to 22. Certain exceptions, however, will be noted in which terms other than the outputs of the N flip-flops will be required to establish the state. For example, the right hand input terms for the gates of state terms 0, 1 and 2 (FIG. 20) and terms 73 to 77 (FIG. 22), all occurring in the divide routine, require the inclusion of the term $\div$. Thus, partial product $N_4N_5'N_6'$ $\div$ is solved by gate 172 (FIG. 19), requiring that the divide term $\div$ be supplied, as will be described later on, to satisfy the right hand input for those gates.

The solution of certain logical equations throughout the computer require the logical product or sum or combined product and sum of two or more state terms. Various such combined state terms are solved by different ones of a series of program counter or state term gates shown in FIGS. 23 to 26, inclusive. For example, the logical sum $6+32+76+53+56$ is solved by combined logical sum gates 188 and 190 (FIG. 24).

MASTER PROGRAM FLIP-FLOP M

As noted heretofore, the master flip-flop M (FIG. 27) controls the program counter to advance consecutively, skip forwardly or backwardly to certain other states, or to "stick" in one state. Thus, the output of the M flip-flop in combination with certain combined state terms mainly controls the N flip-flops shown in FIG. 16. The equations for the M flip-flop are quite complex and will be developed as the description proceeds. In general, when the M flip-flop is set true it will control the program counter to advance to the next successive state and when it is set false, it will control the counter to skip or to stick in its current state.

STATE COUNTER INPUT CONTROLS

Going back to the logical equations for controlling the program counter (FIG. 16) it will be seen that the equations for N_1 are $n_1=[M'(6+32+76+53+56)+M]N_1'P_nC$, and $on_1=[M'(17+42+43+44+45)+46+47+50+51+52]+M]N_1P_nC$.

The n_1 equation indicates that when N_1 is set false at the end of a word time (P_n) and at the occurrence of a clock pulse (C), if M is set true, N_1 will be set true, or when N_1 is set false at P_n and at the occurrence of a clock pulse C , if M is set false at state #6, #32, #76, #53 or #56, N_1 will be set true. The latter identified states #6, #32, etc., represent those states from which the counter skips to a non-consecutive state and wherein N_1 is to be set true regardless of whether N_1 was previously set true or false.

On the other hand, the on1 equation indicates that when N1 is set true at Pn and at the occurrence of a clock pulse C, if M is set true, N1 will be set false, or when N1 is set true at Pn and C, if M is set false at states #17, #42, #43, #44, #45, #46, #47, #50, #51, or #52, N1 will be set false.

Here the latter identified states represent those states from which the counter skips either forwardly or backwardly to a non-consecutive state and wherein N1 is to be set false regardless of whether N1 was previously set true or false.

The equation for n2 indicates that when N2 is set false and at Pn and C, if N1 is set true and M is set true, N2 will be set true or when N2 is set false at Pn and C, if M is set false at state #64, #71 or #75, N2 will also be set true. The states #64, #71 and #75 are those from which the counter skips either forwardly or backwardly to a non-consecutive state and where N2 is to be set true regardless of its previous condition.

The equation for on2 indicates that when N2 is set true at Pn and C, if N1 is set true and M is set true, N2 will be set false, or when N2 is true at Pn, C, if M is set false at state #23, #62, #76, #42, #43, #44, #45, #46, #47, #50, #51, #52 or #77, N2 will be set false.

The equations for the remaining flip-flops N3 to N6 should be self-evident from an inspection of FIG. 16. However, in the equation for setting N4 false, the sub-product 32 $\times$, in order to be solved, requires that the computer be in state #32 and the multiply key $\times$ (FIGS. 1 and 57) be depressed.

It will be noted that each higher order flip-flop requires, in order to set the same in response to a true setting of M, the product of the true terms of all lower order N flip-flops in addition to other terms.

The physical solution of the input equations for the N flip-flops is shown in FIG. 18. It should be noted first that the term Pn C is common to all input equations and is, therefore, omitted in the latter figure, but instead is solved by a separate product gate 181 (FIG. 18A). The output Pn C is fed directly, as indicated at 182 (FIG. 16), to one input leg of each of the various gates directly associated with the N flip-flops. Likewise, for the sake of simplicity, the connection between the true output of each flip-flop and the false input thereof, and the connection between the false output and true input thereof are omitted in FIG. 18 since such connections are considered incorporated in the flip-flop circuit itself as indicated in the block diagrams of FIG. 16.

Accordingly, the term M, necessary in certain combinations to set the N1 flip-flop true, is entered directly through a diode 183 to the n1 setting line 184. The terms M' and $6+32+76+53+56$ are entered in separate inputs of a product gate 185 to likewise set N1 true. It should be noted that the diode 183 and the gate 185 are connected to the line 184 in a logical sum relation in that this line is connected to a negative potential supply through a resistor R25.

Correspondingly, it will be noted that the term M is directly connected through diode 183 to the on1 line while the term

$$M' (17+42+43+44+45+46+47+50+51+52)$$

is generated in a product gate 186, the output of which is connected to the on1 line.

Since each correspondingly higher order N flip-flop requires the product of the true terms of all lower order flip-flops, when combined with M to effect setting of the same in either of its true or false conditions, the same M and N inputs are used for all solutions and are merely added to each other in a logical product relation as the higher order N flip-flop entries are solved. Thus, N6 is set true in one case by the product of terms M

N1 N2 N3 N4 and N5, when N6 is false and at Pn C. This term is generated by gate 189.

STATE PROGRAM COUNTER SUMS

5 The solution of certain logical equations throughout the computer require the logical product or sum or combined products and sums of two or more state terms. Various such combined state terms are solved by different ones of a series of program counter or state term 10 gates, shown in FIGS. 23 to 26, inclusive. For example, the logical sum $6+32+76+53+56$ is solved by combined logical sum gates 188 and 190 (FIG. 24), and this combined term is used to control one of the inputs of gate 185 (FIG. 18).

SECOND PRINT CONTROL FLIP-FLOP Z

Since the capacity of the machine is one word length or nineteen decimal digits plus one digit which is used at times for registering the sign, and since the capacity 20 of the printer is less than this amount, it is possible in some cases that the amounts to be printed may exceed the capacity of the printer. Also, the format switch (FIG. 56) may be set to restrict the number of digits printed on any one line by the printer to less than its 25 full capacity. In such cases, and upon setting the switch 42 (FIGS. 11 and 60) in an appropriate position, that portion of an amount not printed on one line will automatically be printed on a second line. This control is effected mainly by a Z flip-flop (FIG. 28) whose input 30 equations are solved mainly by the diode net shown in FIG. 29.

LOGICAL FLIP-FLOPS

In performing the various arithmetic operations and in advancing through the different computer states, certain 35 logical operations are performed. For this purpose, a series of seven K flip-flops and associated diode nets are mainly employed. Such flip-flops are used alone or in various combinations for such purposes as shifting data in 40 the memory lines on the magnetic drums, filling data in the memory lines, for displacing data in one memory line relative to another, for remembering signs, for inserting certain constants, etc. Such K flip-flops are shown in block diagrams in FIGS. 32 and 33, along with the logical 45 equations for controlling the same.

It will be seen from a general inspection of the logical 50 equations for the K flip-flops that the latter are controlled mainly by various logical products and sums of state terms, sync indications and key controlled switches and the various aforementioned flip-flops associated with the read heads for various memory lines. For example, K1 55 may be set by the logical product of F5 and any of the state terms 13, 14, 15, 16, 17, 26, 27, 30, 31 or 32.

The equations for controlling the various K flip-flops 55 will become more apparent as the description of the various other circuits involved in the solution of such equations are discussed.

The logical nets for controlling the inputs to the various K flip-flops are shown in FIGS. 34 to 39, inclusive. 60 For example, the aforementioned composite term F5 ($13+14+15+16+17+26+27+30+31+32$) is physically solved by the logical product gate 195 (FIG. 34). Such term, when passed by the gate 195, sets the K1 65 flip-flop true.

RECORD FLIP-FLOP CONTROL CIRCUITS

The various record heads associated with the magnetic drum 101 (FIG. 2), are, as described before, controlled by various record flip-flops AR1, AR2, ER, FR and GR.

70 Considering first the control circuitry for the two flip-flops AR1 and AR2 associated with the record head for the A line, the inputs ar1 and oar1 for AR1 are generated by a logical product gate 196 (FIG. 40) and a 75 logical sum gate 197, respectively. Likewise, the inputs

ar2 and *oar2* are generated by a logical product gate 198 and a logical sum gate 199, respectively.

The inputs *A0*, *A0'*, *AR* and *AR'* of the above gates are generated by the logical nets of FIGS. 41 and 42. The net of FIG. 41 determines the information or data to record in the *A* line while the net of FIG. 42 determines when the terms generated in the net of FIG. 41 are to be recorded on the *A* line.

It will be seen that the input information *A0* (FIG. 41) is fed through an inverter 200 to obtain the logical inverse *A0'* which is needed as an input term in controlling the gates 197 and 198. The input information *AR* is also fed through an inverter 201 to obtain the logical inverse *AR'* which is used as an input term in gates 197 and 199.

The diode net of FIG. 43 for controlling flip-flop ER is composed of a number of logical sum and product gates to provide an output *E0*. The latter term, as seen in FIG. 2, forms the input *er* for one input of record flip-flop ER. The term *E0* is also passed through an inverter 202 to obtain the logical inverse *oer* applied to the second input of ER.

Similarly, the output *F0* of the diode net in FIG. 44, is applied as *fr* to flip-flop FR. The same term *F0* is passed through an inverter 203 to obtain the term *ofr* which is applied to the second input of FR.

Likewise, the output *GO* of the diode net in FIG. 45 is applied as input *gr* to flip-flop GR. The same term is passed through inverter 204 to be applied as *ogr* to the second input of GR.

It will be noted on inspection of FIG. 43 that the product gate 205 herein includes an input "E Recirc.". The latter term is generated by a diode net of FIG. 46 whose output is passed through an inverter 206 to form the term *E Recirc.* The terms for the inputs to the various gates of the diode net of FIG. 46 are found to comprise mainly various state terms combined with certain K flip-flop terms.

The terms "F Recirc." and "G Recirc." are generated by the nets of FIGS. 47 and 48, respectively, in a manner similar to the term *E Recirc.*

F FLIP-FLOP CONTROL

It will be recalled that the F2 to F5 flip-flops (FIG. 2) are cascaded and may be controlled by flip-flop F1 in transferring information from the *F* line of the recirculating channel or they may be controlled independently of F1 by the machine logic. For this purpose, a diode net, shown in FIG. 49, is provided, the outputs *f2* and *of2* of which are connected to correspondingly identified inputs of flip-flop F2.

The term ΣFG and $(\Sigma FG)'$ required as inputs in the diode nets for flip-flop F2 are generated by the diode net shown in FIG. 50. It will be noted that the output ΣFG is passed through an inverter 208 to obtain the term $(\Sigma FG)'$.

FIGS. 51 to 53 illustrate additional diode nets which are used to develop terms used as inputs in the diode matrices of FIGS. 43, 44 and 45.

DECIMAL POINT CONTROLS

According to the present invention, the decimal point position of factors and results may be preset as desired by a decimal point switch 210 (FIGS. 1 and 54). The latter is shown as set at "3" indicating that the decimal point position will be between the hundredths and thousandths denominational position in all factors and results.

FIG. 55 illustrates the diode net for generating the term DP Set under control of the decimal point switch and various identified state terms.

KEYBOARD LOGIC

The various keys and settable levers, forming part of the keyboard shown in FIG. 1, all control certain switches which make up certain portions of the machine logic and which control the machine circuitry in accordance with the functions assigned to the particular keys. Such keys and their associated switches and circuitry are shown in FIGS. 57 to 61, inclusive. The various amount keys (0) to (9), schematically indicated in FIG. 57, are directly connected to respective single pole, double throw switches, like switch 219, which are normally (when the keys are in their undepressed positions) in their upper illustrated positions. The back space key 15 is likewise connected to a similar switch.

Each of the above amount key and back space key switches has its break contact connected to the armature of the next succeeding switch so that when all such keys are up, a circuit will be completed from an input *t-6* to an output *T-6*. A delay circuit comprising a capacitor C10 and a resistor R11 in series with each other across a load resistor R12, is connected between the input *t-6* and a source of minus 30 volts to eliminate any detrimental effects resulting from key switch bounce.

The *t-6* input is connected in circuit with a source of plus 10 volts supply 309a (FIG. 67) through certain control relays to be described later, while the output *T-6* is connected to an input leg of a product gate 448 (FIG. 39) to indicate a true condition *T-6* when all amount keys and the back space key are undepressed. The term *T-6* is logically multiplied by the terms *P2 Sync* and *4'* to set the K6 flip-flop true in state #3.

A circuit *T-6R* is connected between *t-6* and an input *T-6R* of product gate 435 (FIG. 31), the input *T-6R* being high when relays 311, 324 and 325 are all deenergized.

A second input *T5'* of gate 435 is connected through an inverter 209 (FIG. 57) and diodes, like diode 209a, to the make contacts of the amount key controlled switches.

The make contacts of the amount key switches are connected to "set true" and "set false" inputs of certain of the K1 to K4 flip-flops, through a diode matrix, generally indicated at 212 (FIG. 57).

In this regard, it should be understood at this time that the flip-flops K1 to K4 are normally set by the pulse counter in a relative binary condition representing the decimal digit 5, i.e., the flip-flops are set as follows, K1=0, K2=1, K3=0, K4=1. That is, K2 and K4 are normally set true and K1 and K3 are normally set false. Because of this, the connections from the amount key switches are such as to set the K1 to K4 flip-flops from their normal conditions representing 0101 to other conditions representing the binary equivalent of the decimal value of the amount key depressed. Accordingly, four flip-flop setting lines *k1*, *ok2*, *k3* and *ok4* are provided and are connected to the various amount key switches through appropriate diodes. For example, the make contacts of the (0) key is connected through diodes 213 and 214 to the *ok2* and *ok4* lines, respectively. When the (0) key is depressed, K2 and K4 will be set false (see FIGS. 33 and 35), and since K1 and K3 are normally false, all flip-flops K1 to K4 will be set false to represent a 0.

Also, when the (9) key is depressed, positive potential will be applied from *t-6* through all break contacts of the lower valued key switches and through appropriate diodes connected with the make contact of the (9) key switch to raise the potential of lines *k1* and *ok2*, thus setting K1 true and setting K2 false. Accordingly, since K3 and K4 are not changed from their normal settings of 0 and 1, respectively, the K1 to K4 flip-flops will register 1 0 0 1.

The various storage accumulator selecting keys A1 to A10 (FIG. 57) are likewise connected to single pole, double throw switches whose break contacts are each connected to the armature of the next preceding switch, with the exception of the absence of a connection between A1 and A2. Accordingly, when all accumulator selection keys A2 to A10 are up, the term (A2-10)' is generated. For this purpose, the armature of the switch for key A10 is connected to a plus 10 volt source 220 and the output line (A2-A10)' is connected to a source of minus potential through a load resistor R13. A diode 215 connected to ground clamps the output to ground potential when any selection key A2 to A10 is depressed. Otherwise, when all such keys are in raised position, plus 10 volts will be applied to generate the term (A2-10)'.

A second output (A3-10)' is connected to the break contact for the switch of key A3 so as to generate the term (A3-10)' when all of the keys A3 to A10 are up and regardless of the position of key A2. This output is also clamped at ground potential by an associated diode when any of the accumulator selection keys A3 to A10 are depressed.

The make contacts of the A1 to A10 key switches are connected to certain ones or certain combinations of the flip-flop inputs k1, ok2, k3 and ok4 through a diode matrix generally indicated at 216 and through logical product gates 222 to 225. Such gates are controlled by terms generated by depression of certain of the machine control keys, such as the plus key, minus key, etc., as will appear later.

Each of the make contacts of all the A1 to A10 key switches is normally held at a minus ground potential by connection to negative sources of potential through load resistors, like R14, and are clamped at ground potential by diodes, like diode 221, having their anodes connected to ground.

The remaining machine control keys and switch levers are shown in FIGS. 58 to 61. These switches, in general, generate single terms identified by similar names or symbols for which the particular associated keys are identified. However, it will be seen that some of the key switches, also, generate the prime of a term when in raised position. For example, the switch for the "Reset A" key 27 of FIG. 58 generates the term "Reset" when the reset A key is depressed, and the term "Reset" when the key is undepressed.

It will be noted that the break contacts of the various key switches for the reset A key 27, memory clear key 45, print only key 24, quotient key 13, remainder key 33, subtotal key 23 and total product key 20 are connected in series to a plus 10 volt supply in a manner similar to the switches for the amount and accumulator selection keys so as to normally, when all such keys are raised, generate the term (MC-T)' over the similarly identified output.

The break contacts of the switches for the enter-plus key 36, enter-minus key 35 and clear A key 26 are connected in series to an input A1-10 derived from a similarly identified output of the diode matrix 216 (FIG. 57). Thus, the input A1-10 in FIG. 57 is rendered high in potential when any one of the accumulator selection keys is depressed.

It will be noted that the break contacts for the switches for the plus key 17 (FIG. 59), multiply key 22 and divide key 31 are also connected in series relation to a plus 10 volt supply so as to generate the term (+×÷)' when such keys are undepressed. Likewise, the break contacts for the switches for the first factor key 21 and dividend key 30 are connected in series relation to a plus 10 volt supply.

Certain composite terms are also generated by certain of the control keys upon depression. For example, the term T+S is generated by depression of either of

the subtotal and total product keys. Also, the term $\otimes + \ominus$ is generated upon depression of either the multiply key 22 or the divide key 31.

Referring back to FIG. 57, it will be noted that the outputs 227 to 230 of the diode matrix 216 associated with the accumulator selection keys A1 to A10 are fed into the left hand inputs of the product gates 222 to 225, respectively. Thus, for example, when the A6 accumulator selection key is depressed, plus 10 volts will be applied from source 220, through all higher valued selection key switches, diodes 401, 402, 403, 404 and 405 and lines 227, 228, 229 and 230 to the left hand inputs of gates 222, 223, 224 and 225, respectively. The right hand inputs to these gates are connected to branches of a common line 1230 which is connected to the output of a logical net shown in the lower half of FIG. 57. The latter net combines certain terms derived from the machine control key switches. The various inputs for the diode net are obtained either directly from the various ones of the machine control switches or from a diode net shown in FIG. 62. Terms forming the input of the net of FIG. 62 are derived from a second net shown in FIG. 63, the latter, in turn, obtaining its terms from the control key switches or from outputs of the net of FIG. 62.

As a further aid in understanding the setting of the K1 to K4 flip-flops under control of the various keys, the following Table A indicates the states of these four flip-flops as an incident to depression of each of the amount keys. The Table B indicates the states of the four flip-flops as an incident to setting of each of the accumulator selection keys and depression of certain computer control keys as will appear later.

55	TABLE A				TABLE B					
	Flip-flop	K1	K2	K3	K4	Flip-flop	K1	K2	K3	K4
40	Normal	0	1	0	1	Normal	0	1	0	1
41		0=0	0	0	0		A1=0	0	1	0
42		1=0	0	0	1		A2=0	1	1	0
43		2=0	0	1	0		A3=0	1	1	0
44		3=0	0	1	1		A4=1	0	0	0
45	Amount keys	4=0	1	0	0		A5=1	0	0	1
46		5=0	1	0	0		A6=1	0	1	0
47		6=0	1	1	0		A7=1	0	1	1
48		7=0	1	1	1		A8=1	1	0	0
49		8=1	0	0	0		A9=1	1	0	1
50		9=1	0	0	1		A10=1	1	1	0

From the above we can establish the logical equations for setting the K1 to K4 flip-flops from their normal 0 1 0 1 relation under control of the various amount and accumulator selection keys. These equations are as follows:

$$\begin{aligned}
 k1 &= 8+9+T+S(A4+A5+A6+A7+A8+A9 \\
 &\quad +A10)[CA+P0+RESET\{\oplus+\ominus+\otimes+\ominus \\
 &\quad +1(+-\times\div<+<-P0)'+D(+ \\
 &\quad -\times\div<+<-P0)'\}] \\
 ok2 &= 0+1+2+3+8+9+Q+R+D(+-\times\div< \\
 &\quad +<-P0)+(A1+A4+A5+A6+A7)[CA+P0 \\
 &\quad +RESET\{\oplus+\ominus+\otimes+\ominus+1(+-\times\div< \\
 &\quad +<-P0)'+D(+-\times\div<+<-P0)'\}] \\
 k3 &= 2+3+6+7+T+S+D(+-\times\div<+<-P0) \\
 &\quad +(A1+A2+A3+A6+A7+A10)[CA+P0 \\
 &\quad +RESET\{\oplus+\ominus+\otimes+\ominus+1(+-\times\div< \\
 &\quad +<-P0)'+D(+-\times\div<+<-P0)'\}] \\
 ok4 &= 0+2+4+6+8+Q+1(+-\times\div<+<-P0) \\
 &\quad +(A1+A2+A4+A6+A8+A10)[CA+P0 \\
 &\quad +RESET\{\oplus+\ominus+\otimes+\ominus+1(+-\times\div< \\
 &\quad +<-P0)'+D(+-\times\div<+<-P0)'\}]
 \end{aligned}$$

The remaining flip-flops K5 to K6 are controlled by propositions involving various state terms and machine conditions as will appear later.

READ-OUT CONTROLS

The outputs from the various K flip-flops are translated into decimal digit terms capable of setting the printer, by a diode net shown in FIG. 66. This net combines the terms 23 Y' with the various K outputs. For example, the outputs K2 and K3' of the respective K2 and K3 flip-flops are passed by a product gate 240, the third input of which receives the terms 23 Y'K4 passed by a gate 239 to produce the term 5, representing the decimal digit 5.

The following table indicates the relationship of the K flip-flops in producing the various printer control terms. It will be understood that the terms 23 and Y' will be combined with the indicated K terms to produce the control terms.

	K1	K2	K3	K4	K6
0=0	0	0	0	0	0
1=0	0	0	1	0	
2=0	0	1	0		
3=0	0	1	1		
4=0	1	0	0		
5=0	1	0	1		
6=0	1	1	0		
7=0	1	1	1		
8=1	0			0	
9=1	0	0	1		

Since the outputs of K2 and K3 are not necessary in determining the term 8, they are omitted.

It will be seen that the terms K2'K3' comprising one of the inputs of a product gate 241 for generating the term 9 is generated by a product gate 242 used to generate such term as a partial product for the term 1.

PRINTER

The output terms as generated by the diode net of FIG. 66 are utilized, as will be described later, to control the entry of amounts through a buffer unit into a ten key listing type printing machine (shown in FIGS. 68 to 72).

The printing machine is basically the well-known Clary ten key adding machine disclosed and claimed in the co-pending Boyden et al. patent application, Serial No. 506,486, now Patent No. 2,989,231, filed May 6, 1955.

The machine has been modified as shown in the A. F. Stansell pending patent application, Serial No. 584,656, now Patent No. 2,917,231, filed on May 15, 1956, to incorporate solenoids for actuating the amount keys so that the latter may be actuated by pulses derived from the machine circuitry. Also, the accumulator and its controls are omitted in the present case, although such items may be retained if desired.

Since the printer, in general, is disclosed in the above pending applications, only those portions of the machine which are novel or which cooperate directly with the present invention will be illustrated and described herein.

In general, the machine comprises a plurality of denominationaly arranged reciprocal drive racks 245 differentially movable under control of a pin carriage, generally indicated at 246, whose stop pins 247 are set in a serial manner by depressing respective ones of ten amount key elements 248.

The amount key elements are depressed by armatures 250 of ten solenoids 251 located directly above the key elements.

When the coil of any solenoid is energized, it will cause its armature to depress the respective amount key element 248 downwardly to rock a respective one of a series of bails 252 whose arms directly underlie pins 253 on the keys (see FIGS. 68 and 71).

The various bails 252 are pivotally mounted independently of each other on a stationary cross rod 254 and are normally held in their upper illustrated positions by individual springs 255. The opposite legs of the various bails 252 terminate in a row of aligned hammer pro-

jections 256 which are located over respective ones of a row of stop pins 247 carried in the pin carriage 246. When the pin carriage is located in its home or right hand position, shown in FIG. 71, the hammer projections are located over the left hand row of pins 247.

Thus, when a key element is depressed by its solenoid its associated bail will depress the stop pin aligned with its projection 256 into a position wherein it will arrest a rack 245 in a corresponding numerical position.

The pin carriage 246 is movable laterally of the machine along guide rods 257 and 258 into cooperative relation with different ones of the racks 245.

An escapement mechanism is provided to cause the pin carriage to be stepped laterally to the left from one denominational order to the next as an incident to energizing any key solenoid 251.

As shown in FIGS. 69 and 71, a toothed plate 260 is carried by the pin carriage 246 and has a series of forwardly extending teeth 261 engageable by an upstanding tooth 262 of an escapement lever 263. The latter is pivoted on the rod 254 and is urged upwardly into engagement with the teeth by a spring 255. A universal bail 264 also pivoted on the rod 254 is provided with a web portion 266 underlying all of the key actuated bails 252. A spring 267 normally holds the bail in its upper illustrated position.

As any amount key elements 248 is depressed and the hammer portion 256 of its associated bail depresses a corresponding stop pin 247, the universal bail 264 will be lowered causing a tooth 268 thereon to depress and disengage the tooth 262 from blocking engagement with an adjacent one of the teeth 261. Accordingly, a tensioned spring 241 will be effective to advance the pin carriage to the left a slight amount so that the adjacent tooth will overlie the tooth 262 of lever 263. When the energized solenoid is de-energized and the depressed key element allowed to rise, the universal bail 264 will likewise rise, allowing the pin carriage to continue its advance into the next denominational position whereupon the tooth 262 will again snap upwardly to block the pin carriage.

Referring to FIG. 70, it will be seen that the bail 264 has an extension 264a which normally engages the plunger of a switch 269 to maintain the same in open condition whenever no amount keys are depressed and to allow the switch to close whenever any amount key is depressed.

The machine is driven by a motor (not shown) which is effective during each cycle to rotate a drive shaft 270 one complete revolution in a counterclockwise direction.

Means are provided for yieldably advancing the racks forwardly, i.e., to the left in FIG. 68, until arrested in different numerical positions by depressed ones of the stop pins 247 on the pin carriage and for thereafter returning the racks after a printing operation. For this purpose, a pair of juxtaposed cams 410 and 411 are keyed on the shaft 270 and are engaged by rollers 271 and 272, respectively, mounted on a cam follower 274. The latter is pivoted on a cross rod 273 forming a sliding support for the gear ends of the various racks and is connected by a link 279 to a bifurcated arm 275. This arm is fastened to a rock shaft 276 and its bifurcation embraces a roller 277 rotatably mounted on one end of a rack drive shaft 278. A similar roller (not shown) is provided on the opposite end of the shaft 278 and is embraced by an arm similar to arm 275 to insure parallel movement of the shaft 278 during its rack drive movement.

The shaft 278 is guided for fore and aft movement in a direction transverse to its axis by suitable guide means (not shown) and is embraced by slots 280 formed in the various racks to guide the left hand ends of such racks.

The slot 280 in each rack terminates in opposed lateral notches 281, each of which is engaged by a roller carried on the drive element 282 which is pivotally supported on the shaft 278. Two such drive elements are associated with each rack and are spring urged in opposite directions about the shaft 278 by tension spring 283 so as to yield-

ably hold the rollers 282 of the drive elements in engagement with respective ones of the notches 281.

At the start of a machine cycle, rack stop elements 284, pivoted at 285 to extensions of the various racks, are raised by a bail 286 into upper positions indicated by the dot-dash lines 284a. In these positions, stop shoulders 287 on the stop slides are located in positions to be blocked by depressed ones of the stop pins 247. Thus, during the forward advancement of the racks 245, during the first part of the cycle, and when any stop element 284 is arrested by an aligned depressed stop pin 247, the drive elements 282 associated with the respective rack will ride out of the notches 281 against the action of spring 283, thus breaking the connection between the shaft and the rack.

Each rack is effective during advancement thereof to set a respective printing wheel 291, preparatory to a printing operation, through a train of gears 288, 289 and 290. The latter meshes with the extension of the associated rack.

The printing wheels 291, having the type characters 0 to 9 located therearound, are carried by respective arms 291a mounted on a printer control shaft 292. In mid-cycle, and after the racks have been differentially advanced to the left, the shaft 292, which is loosely keyed to the various arms 291a is rocked clockwise under control of the drive shaft 270 through linkage (not shown), permitting the arms 291a to be swung clockwise under the action of individual springs 294 to effect printing of amounts set upon the type wheels, through a printing ribbon 300 and onto a paper tape 301 supported by a platen 302. Immediately thereafter, the shaft 292 is returned counterclockwise to pick up the arms 291a and then remesh the gears 289 with their associated gears 290. Thereafter, the racks 245 are returned to the right by the shaft 278 and drive elements 282, to their illustrated home positions.

The three right hand printing wheels (not shown) are reserved for symbol printing and, accordingly, each as symbol type characters therearound in lieu of the usual numeral printing type. In other respects, however, these wheels and their actuating devices are the same as the numeral printing wheels and their actuating devices.

During the latter half of each cycle, i.e. while the racks are being returned from advanced positions, suitable means (not shown) are actuated to return the pin carriage to the right, in FIG. 71. As the lower ends of depressed ones of the stop pins engage a stationary cam plate 295, they are cammed upwardly into their normal raised positions.

The printing ribbon 300 is divided into an upper black section 300b and a lower red section 300r for printing certain types of amounts in different appropriate colors. The ribbon is guided past the printing station in a path parallel to the length of the platen 302 by two spaced arms, one of which is indicated at 338. These arms are pivotally supported on coaxially extending pivot studs 339.

The opposite ends of the ribbon 300 are suitably guided around the arms, over the pivot studs 339, and are wound on supply and take-up ribbon spools (not shown).

Both ribbon arms are urged in a counterclockwise direction by springs, like spring 340, but are normally held in a lowered position illustrated in FIG. 72 by arms, like arm 341, securely keyed to the printer control shaft 292, and engaging studs, like stud 342, secured to extensions of the arms.

At the start of a printing operation and as the printer control shaft 292 is rocked clockwise, the arms, i.e. 341, recede from engagement with the pins 342, thus allowing the ribbon guiding arms to raise the ribbon into printing position.

Means are provided for controlling the positioning of the ribbon with either its black section 300b or its red section 300r on the printing line. For this purpose, links,

one of which is shown at 343, are pivotally connected at their upper ends to extensions of the ribbon arms and are provided at their lower ends with vertical slots guided over stationary frame pins, like pin 344. Studs, i.e. 345, 5 on the links 343, extend inwardly under the overlying ledge of a bail 346 which is pivoted at 347 and pivotally connected at 348 to a link 349. The latter is pivotally connected to a lever 350 fulcrumed at 351 and pivotally connected at its lower end to an armature 352 of a solenoid 353, the latter being suitably supported by the frame of the printer.

Normally, when a black color print is to be made, the bail 346 is maintained in its illustrated position by a spring 354 connected to a pivot pin 355 which connects the link 15 349 to the level 350. In this condition, and at the start of a printing operation, the ribbon guiding arms will be allowed to rise under the influence of their springs until the pins 345 engage the overlying shelf of bail 346. The ribbon guiding arms will now rise only to an extent to 20 position the black section 300b of the ribbon on the printing line, the ribbon at this time assuming a position indicated by the dot and dash line 300c.

Upon energization of the solenoid 353, in a manner to be described, hereafter, the lever 350 will be rocked counterclockwise to actuate link 349 and thus rock the bail 346 clockwise sufficiently to permit the ribbon guiding arms to rise (during the printing operation) to a higher level wherein the red printing section 300r of the printing ribbon will be located on the printing line, in which case 30 the ribbon will assume a position indicated by the dot and dash lines 300d.

The latter setting of the bail 346 will be maintained, until other controls are effected, by a latch 356 fulcrumed at 357 and urged downwardly by a spring 358. 35 As the solenoid 353 is energized and the lever 350 rocked counterclockwise, a shoulder 359 on the latch will drop behind a roller 360 rotatably mounted on the pivot pin 355, thus, latching the bail 346 in its red print controlling position.

40 During such energization of the solenoid 353, the lever 350 will be over-thrown slightly beyond its position located by the latch 356 and in so doing, a projection of such lever will strike the actuating element 361 of a switch 362, thereby momentarily completing a circuit connected to such switch.

45 Means are provided to return the printer to its black print controlling status. The latch 356 is connected to the armature 363 of a solenoid 364 suitably supported by the frame of the printer. Upon energization of the solenoid 364 its armature will retract the latch 356 against 50 the action of springs 358 and thus permit the bail 346 to be returned to its illustrated black print control position.

The solenoid 364 upon energization will cause the latch 356 to be over-thrown slightly beyond its position shown in FIG. 72, and in so doing, the latch will engage the actuating element 365 of a second switch 366 to thereby 55 momentarily complete a circuit in which this switch is connected.

60 The printer is provided with an additional normally closed switch 321 (FIG. 73). The latter is suitably mounted on the frame of the printer and is actuated to momentarily open the circuit in which it is connected during a latter portion of the printer cycle by a cam 367 keyed on the drive shaft 270.

PRINTER CONTROLS

70 The buffer unit for actuating the various amount key solenoids 251 (FIGS. 68, 69 and 71) of the printer in response to signals received from the outputs of the diode net of FIG. 66, comprises a series of ten thyratron type gas filled tubes, one of which is shown at 304 in FIG. 67. The anodes of these tubes are connected in circuit with respective ones of the solenoids 251. The cathodes of these tubes are connected to a plus 10 volt supply line 75 305 which is isolated from other 10 volt supplies

throughout the machine circuitry. The igniters of the various thyratrons are biased to ground potential by biasing resistors, one of which is shown at R18, to a common ground line, thus normally maintaining the thyratrons in their non-conducting conditions.

The igniters of the tubes are connected through suitable terminal connections 1306 to similarly numbered outputs of the diode net in FIG. 66.

The opposite ends of the amount key solenoids 251 for the key elements "0" to "9" are all connected to a common B plus line 306 which is normally connected to a B plus supply 337 through normally closed contacts 308 and 309 of a feedback relay 310 and a print relay 311, respectively.

Thus, when a term is generated in any of the amount digit outputs of FIG. 66, the corresponding thyatron tube will be fired to energize the respective amount key solenoid 251 and thus enter the correspondingly valued digit in the printer by depressing an appropriate stop pin 247 in the pin carriage of the latter.

As the universal bail 264 (FIG. 70) is lowered in response to setting of the appropriate stop pin 247, the switch 269 will be closed to apply 150 volts B plus from a source 312 through the coil of feed-back relay 310 to the plus 10 volt cathode line 305, thus energizing the feed-back relay and breaking the B plus circuit to the amount key solenoids 251. Accordingly, a depressed amount key will be allowed to rise and the fired thyatron tube will be extinguished.

It will be noted that a delay circuit comprising series connected capacitor C26 and resistor R26 are applied across the coil of relay 310 to insure proper operation of the key elements and stop pins of the pin carriage in the printer.

It will also be noted that the feed-back relay 310 includes a transfer contact 313 connected to a plus 10 volt supply which is normally engaged with a break contact connected to a line 314 extending to a terminal "FB Open," thereby normally maintaining this switch terminal at a relatively high potential. This terminal is connected as an input to certain logical net product gates (see, for example, FIG. 30).

The make contact associated with transfer contact 313 is connected through a line 315 to a terminal "FB Closed" which, also, is connected as an input to certain net gates as shown in FIG. 30.

Both lines 314 and 315 are connected through load resistors R20 and R21 to a source 316 of B minus potential. However, when either of such lines is open, it is clamped to ground potential by one or the other of two diodes 317 connected to ground. It will thus be seen that one or the other of the terminals "FB Closed" and "FB Open" will be at a high potential, depending on the condition of the relay 310.

Initiation of operation of the printer is effected in computer state #24. Accordingly, the state term 24 is connected through a similarly numbered terminal and line 318 (FIG. 67) to the igniter of a print thyatron tube 320. The latter is normally held in non-conductive condition, its cathode being connected to the plus 10 volt line 305 and its igniter being biased to ground potential through a biasing resistor R22. When the term 24 is rendered high, i.e. when the computer reaches state #24, the thyatron 320 will be fired completing a circuit from its anode through the coil of print relay 311, resistor R23, and normally closed switch 321 (see also FIG. 73) to a 150 volt B plus supply. Accordingly, the print relay will be energized to close normally open contacts 322 and thus complete a circuit through a printer operation initiating solenoid 323, thereby initiating operation of the printer. That is, the solenoid 323 is connected in a suitable manner (not shown) to the clutch control dog, i.e. dog 102 in FIG. 3 of the aforementioned Boyden et al. application Serial No. 506,486, so as to engage the cyclic drive clutch for the main shaft of the printer. The con-

tacts 309 will now open to prevent energizing of any of the amount key solenoids during operation of the printer. At approximately 270° in the printer cycle, the cam 367 (FIG. 73) will open switch 321, thereby dropping the print relay 311 to deenergize solenoid 323 and to again render thyatron 320 non-conducting.

Two additional relays 324 and 325 are provided to insure proper operating relation between the keyboard, the machine logic and the printer, and to effect safety interlocking functions.

When deenergized, the relay 324 applies a relatively high potential of plus 10 volts through line 325a to an output terminal II' and a relatively low ground potential through line 326 to output terminal II. These outputs are employed as input terms to the diode nets for setting the K5 flip-flop (FIG. 38) to true and false conditions.

Also, when deenergized, the relay 324 completes a circuit to output t-6 through normally closed contacts 328 of relay 325, line 329, normally closed contacts 330 of the print relay 311 to plus 10 volt supply to thereby normally maintain the output t-6 at high potential, indicative of the fact that the printer is not operating.

The relay 324 is controlled by a thyatron tube 331 whose anode is connected in circuit with a coil of relay 324, load resistor R23, normally closed contacts 332 of relay 325 and a 150 volt B plus supply. The cathode of the thyatron 331 is connected to the plus 10 volt line 305 and the igniter is biased to ground through resistor R24 to normally maintain the thyatron in non-conducting condition.

When the "Thy II" output of the diode net of FIG. 63 rises in response to depression of certain of the machine control keys, the latter will fire the thyatron tube 331, thus energizing the relay 324 to render the term t-6 false.

The relay 324 will now reverse the conditions of the II and II' outputs, rendering II high and II' low. Relay 324 will also complete a circuit from a 150 volt B plus supply, through its lower make contact, resistor R25 and the coil of relay 325 to the anode of a control thyatron 334. The latter is normally held in non-conducting condition, its cathode being connected to the plus 10 volt line 305 and its igniter biased to ground. The relay 324 will be maintained energized by its thyatron 331 and the relay 325 will remain deenergized until the computer advances to its computer state #3 at which time the terminal No. 3 (FIG. 67) will have a high potential applied to it from the No. 3 output of the appropriate net (shown in FIG. 20) to fire the thyatron 334 and thus energize relay 325.

The relay contacts 332 will now open the circuit through the coil of relay 324, permitting the latter to drop out. At the same time, contacts 336 of relay 325 close to apply 150 volt B plus over line 339 (see also FIG. 59), through the break contacts of the release key switch to energize the key release solenoid 337 to thereby release any set conditionning keys on the keyboard. Relay 324, upon becoming deenergized, opens the circuit through the coil of relay 325, thereby also allowing the latter to become deenergized after having energized the key release solenoid.

FILL ROUTINE

As noted heretofore, the computer advances through certain routines or groups of states, as indicated in FIG. 15, in performing certain types of operations. These routines are normally determined by depression of certain control keys and the consequent closure of respective switches to generate certain controlling propositions. Certain of such propositions initiate setting of the program counter N1 to N6 in appropriate routines whereupon it will advance through the states of these routines under control of the master flip-flop M.

Normally, however, following completion of a calculation, the computer is automatically set in its post state #3 (FIG. 15) of a "Fill" routine. Here, the computer will be conditioned for reception of new amount or control information, as will be seen later. Then, the computer will

advance to its rest state #4 where it will remain until depression of an amount of control key.

Upon entry of each decimal digit through one of the amount keys 0 to 9, or upon depression of the back space key 15, the computer will progress through the fill routine, starting from rest state #4 and advancing sequentially through states #5 and #6. If a digit has been entered, the computer will again return to state #4 where it remains until depression of a new key.

State #4

In rest state #4, the E line is recirculated. This condition will be found to exist by reference to the logical net shown in FIG. 46 wherein it will be seen that because of the inverter 206, the "E Recirculate" term will be high whenever all of the gates thereof are closed. In other words, "E Recirculate" will normally be high except when a proposition is generated by one of the logical gates of the inverter. Since state #4 is not found as an input to the (E Recirc.)' net, the term "E Recirculate" will be high when the computer is in this state and the term is entered as an input in gate 205 (FIG. 43). Accordingly, when read flip-flop E5 is set true by information received from the E line indicative of the binary digit 1, the term E0 is generated by gate 205 to set the record flip-flop ER true. Thus, information contained in the E line will be recirculated therein.

The "F Recirc." and "G Recirc." nets of FIGS. 47 and 48, respectively, are found to have the same characteristics as the "E Recirc." net by virtue of the inclusion of inverter circuits therein. Accordingly, since the state term 4 is not found to be an input in the "G Recirc." net of FIG. 48, the term "G Recirculate" will be high when the computer is in such state #4. Thus, when the flip-flop G5 is rendered true as an incident to transmission thereto of information from the read head of the G line through flip-flops G1 to G4, the term G0 will be generated by product gate 368 of FIG. 45. The G record line flip-flop GR will be set true and the information, therefore, recorded on the G line. Thus, the G line will, in effect, be recirculated in time with the information recirculated in the E line.

The term 4 is found to be part of the logical sum term $4+63+64$ passed by a sum gate 437 of FIG. 23 and applied as an input in a logical sum gate arrangement in the (F Recirc.)' net of FIG. 47. Accordingly, in state #4 the term "F Recirculate" will be low and the F line will not be recirculated. That is, a gate 438 (FIG. 44) incorporating the input "F Recirculate" will be closed. However, the contents of the E line are fed into the F line in addition to being recirculated in the E line. This provision is for the purpose of possibly recalling information from the F line during the fill routine to enable back space operations. For this purpose, the output E5 from the E line read flip-flop E5 is gated during state #4 into the record flip-flop FR for the F line through the gate 430 of the F0 record net of FIG. 44.

The logical flip-flops K1 to K4 have been previously set in the post state #3 to register the binary number 0101, equivalent to the decimal digit 5, as will be explained later. This condition will not be changed during state #4. Likewise, K6 will have been set true and this condition will not be changed in state #4.

During a digit filling operation, the K5 flip-flop is set true to permit recirculation of the E line. However, in the event that the correction key 16 is depressed while the machine is in its rest state #4 for the purpose of clearing any amount previously and erroneously entered, the term "Corr" generated by the switch of the correction key (see FIG. 59), will be passed by a product gate 432 (FIG. 38) to set K5 false. This will have no other effect in state #4, but, subsequently, when the machine advances to its state #5, the term K5'S will be passed by

a gate 433 of the E Recirc. net (FIG. 46), thereby dropping the E recirculate term. It will be seen that K5, when set true, indicates that a digit filling operation has occurred, whereas, when set false, K5 indicates that the correction key has been depressed or that the last operation was a computing operation.

As was stated heretofore, the computer will be advanced from one state to another by the program counter under the initiating control of the master M flip-flop when the latter is set true. In state #4, M will hold the computer in such state while it, (M), is set false and will enable it to proceed into state #5 upon depression of an amount key which is effective to set M true.

Referring now particularly to FIGS. 6, 30 and 48A, the term Pn4 is passed by product gate 434 of the set m net in FIG. 30, indicating the M is set true. As indicated in FIG. 48A, since the M flip-flop will be set true in response to the trailing edge of the Pn pulse, M will be set true during the first pulse time, i.e., P0, in the Y portion of each word time which passes by while the computer is in state #4. However, as noted in FIG. 31, the term Y T-6R T5'4 is passed by the product gate 435 to normally return M to its false state during the same pulse time that it was set true, as long as T-6R T5' is true; that is, as long as all amount keys are underpressed and the relays 311, 324 and 325 (FIG. 67) are deenergized.

Noting the logical equations for setting the N1 to N6 flip-flops (FIG. 16) and the counter program input nets of FIGS. 18 and 18A, it will be seen that the term Pn and M must occur coincidentally before the condition of the counter flip-flops can be changed to advance the program counter to a new state. Therefore, since Pn and M normally occur out of phase when the amount keys are all up, the program counter will remain in its current state, i.e., state #4, as long as no amount key is depressed or the relays 311, 324 and 325 remain deenergized. However, upon depression of any amount key, the term om will no longer be passed by the gate 435 and M will, therefore, remain in its true condition after having once been set in such condition as an incident to a Pn pulse. Therefore, Pn and M will exist coincidentally before enabling the program counter to advance to state #5.

The computer is also advanced from state #4 upon depression of any of the machine control keys which cause a compute operation. For this purpose, generation of the proposition "Thy II" by the net of FIG. 63 upon depression of any of the appropriate machine control keys and closure of the respective switches to generate the corresponding terms will cause the thyratron 331 (FIG. 67) to fire, thereby energizing the relay 324 to drop the term T-6R. This condition enables M to be set true in the same manner as previously described in connection with depression of any of the amount keys so that the terms Pn and M may occur coincidentally to advance the program counter.

The above operation of the computer in its rest state #4 may be briefly summarized in symbolic form as shown in the following table. In this symbolic form, the propositions indicated at the right of the dashes are entered into the particular memory line or flip-flop input indicated at the left of the dashes.

<u>E0</u>	—E Recirculate
<u>F0</u>	—E5
<u>G0</u>	—G Recirculate
<u>ok5</u>	—Corr.
<u>m</u>	—Pn
<u>om</u>	—Y T-6R T5'

The above symbolic form will be followed in discussing the remaining described states in order to condense the description as far as practicable.

The following table indicates in symbolic form the operation of the computer when in its "Set" state #5.

E0—E5 K5

F0—F Recirculate

G0—G Recirculate

$$k1 = 8 + 9 + T + S(A4 + A5 + A6 + A7 + A8 + A9 + A10)[CA + P0 + \text{RESET}\{\oplus + \ominus + \otimes + \ominus + 1(+ - \times \div < + < - P0)' + D(+ - \times \div < + < - P0)' + \}]$$

$$ok2 = 0 + 1 + 2 + 3 + 8 + 9 + Q + R + D(+ - \times \div < + < - P0)' + (A1 + A4 + A5 + A6 + A7)[CA + P0 + \text{RESET}\{\oplus + \ominus + \otimes + \ominus + 1(+ - \times \div < + < - P0)' + D(+ - \times \div < + < - P0)' + \}]$$

$$k3 = 2 + 3 + 6 + 7 + T + S + D(+ - \times \div < + < - P0)' + (A1 + A2 + A3 + A6 + A7 + A10)[CA + P0 + \text{RESET}\{\oplus + \ominus + \otimes + \ominus + 1(+ - \times \div < + < - P0)' + D(+ - \times \div < + < - P0)' + \}]$$

$$ok4 = 0 + 2 + 4 + 6 + 8 + Q + 1(+ - \times \div < + < - P0)' + (A1 + A2 + A4 + A6 + A8 + A10)[CA + P0 + \text{RESET}\{\oplus + \ominus + \otimes + \ominus + 1(+ - \times \div < + < - P0)' + D(+ - \times \div < + < - P0)' + \}]$$

The above indicates that if K5 is true, indicative of a digit filling operation, the E line will be recirculated, i.e., the gate 433 of FIG. 46 will be closed and the "E Recirculate" proposition will be high whereupon the gate 205 of FIG. 43 will pass the proposition E0 to recirculate the E line. However, if K5 is false, as determined by depression of the correction key or following a computing operation (which has established a recall), the gate 433 of FIG. 46 will pass the proposition K5' to drop the term "E Recirculate." Thus, the E line will not be recirculated, and therefore, will be cleared except for the digits filled in Y.

The F and G lines are recirculated since in state #5 the F recirculate and G recirculate propositions are high (see the nets of FIGS. 47 and 48) and are passed by the F0 and G0 nets of FIGS. 41 and 45, respectively.

Depression of different ones of the ten amount keys, the accumulator selecting keys or different computer control keys, as indicated, will effect setting of the K1, K2, K3 and K4 flip-flops in the manners noted from their normal relative settings of 0 1 0 1, respectively. For example, if the amount key 7 were depressed, the term 7 would be applied to the k3 net for K3 (FIG. 32), setting the same true and leaving the K1 to K4 flip-flops in the binary registering condition 0 1 1 1, representing the decimal number 7.

M will remain true in state #5. Consequently, as the term Pn is generated, the program counter will advance to state #6.

STATE #6

The following symbolically represents the operation of the computer in the "Shift" state #6.

E0—K4 (BS)' + F1 (BS)

F0—F5 Y'

G0—G Recirculate

k1—E5

ok1—E5'

k2—K1

ok2—K1'

k3—K2

ok3—K2'

k4—K3

ok4—K3'

k5—II'

ok6—II'

om—II' + Pn

The above indicates that if the back space key has been depressed, the gate 440 of the E0 net in FIG. 43 will open during state #6 so that information from F1 will be entered into the E line. Since, in this case, information is taken from F1 instead of F5 and since the F line is one decimal digit shorter than the E line, this information will be shifted in a direction to present each digit in the next lower denominational position as it is recorded in the E line.

10 However, if no back space operation is involved, i.e., if an amount key or a computer control key has been depressed to accordingly set the K1 to K4 flip-flops, this information is shifted through these flip-flops onto the Y portion of the word which is being recirculated in the E line, while information from the E line, i.e. E5, is recorded in K1. Thus the information in the E line is shifted in a direction to present each digit in the next higher denominational position to provide for entry of the next lower denominational digit, if any.

15 If the operation involves entry of a digit, K5 will be set true by the gate 441 of the set k5 net of FIG. 38. Likewise, the proposition 6 II' generated by the gate 441 will be applied to the ok6 net of FIG. 39 so as to set the K6 flip-flop false in response to a digit filling operation.

20 If the operation has been one of filling a digit wherein II' is high, the term 6 II' will be applied to the om net of FIG. 31, setting flip-flop M false to cause the program counter to skip retroactively to state #3. However, if the operation has not been a digit filling operation, i.e., if a computer control key has been depressed, the Pn pulse occurring at the end of a word time will cause gate 442 (FIG. 31) to generate proposition om. Since the triggering action effected by Pn occurs in response to the trailing edge of this pulse, the M flip-flop will be set false at the start of the next successive pulse, at which time it will have already advanced to state #7. In this case, therefore, although the computer will have advanced to the next state #7, the M flip-flop will be set false.

State #3

30 Considering first the case wherein the computer is returned from state #6 to the "Post" state #3 in response to a digit filling operation, the following operation will occur:

E0—E Recirculate

F0—Blank

G0—Blank

k1—B1

ok1—B1'

k2—K1

ok2—K1'

k3—K2

ok3—K2'

k4—K3

ok4—K3'

ok5—II

k6—T—6 P2 S1 S2'

m—K6 P2 S1 S2'

65 The above indicates that, since in a digit filling operation, K5 is set true in state #6, the E recirculate term will be generated by the net of FIG. 46 to recirculate the E line.

70 However, since the term 3 is applied to the F recirculate and G recirculate nets of FIGS. 47 and 48, respectively, no recirculation of the F and G lines will occur and accordingly, permanent magnets 116 and 120 will clear such memory lines to insure against recording of possible transients which might otherwise be recorded during this state.

75 The aforementioned preset code of 0 1 0 1 is entered

31

into the flip-flops K1, K2, K3 and K4, respectively, in state #3. This is accomplished as indicated by causing the output B1 of the pulse counter flip-flop B1 to be gated through gate 443, FIG. 34, to generate k1. Also, to insure proper operation, the output B1' is gated through gate 444 to generate ok1. K2 and K2' are in turn gated through gates 445 and 446, respectively, of FIG. 35 to set K2 accordingly. This procedure is followed for the remaining flip-flops K3 and K4.

K5 was set true in state #6 during a digit filling operation and will remain so set. However, if the operation is a compute operation in which II is high, K5 will be set false.

K6 controls M and prevents the computer from advancing from state #3 as long as any amount key is depressed. For this purpose, K6 is set true by T-6 at P2 S1 S2' (P2 Sync). This proposition is passed by gate 448 to set K6. Since T-6 is high only when all amount keys have been released to raised position, the computer will remain in state #3 as long as any amount key is held depressed. Since M is set true by K6 at P2 Sync time, the computer will be held through a succeeding drum revolution until the next P2 Sync time in which case the proposition m is generated by the gate 449 (FIG. 30). The computer will now advance to state #4 where it is held until a new key is depressed to enter a new digit or to cause the machine to compute.

If the operation has been one of filling a digit wherein II' is high, the term 6 II' is passed by gate 441 of FIG. 38 to set K5 true.

MEMORY LOOK-UP ROUTINE

In performing a calculation and after digits have been properly filled in the E line, as described in connection with the fill routine, or whenever a computer control key has been depressed, the computer will advance through the memory look-up routine involving states #7, #10 and #11.

In state #7, the K5 flip-flop is set in accordance with the particular computer operation key depressed. That is, in those cases which involve a keyboard recall operation, such as +, -, $\times$, $\div$, etc., the flip-flops K1 to K4 will have been retained in their 0101 relation so that the Y portion of the word in the E line registers 0101. In such case, K5 will be left true. However, if a computer control key which does not require recall operation has been depressed, such as the T, S, R, Q, etc., an address code other than 0101 will be recorded in the Y portion, and the flip-flop K5 will be set false. Following the P2 Sync station the computer will advance to state #10. Here the appropriate word section of the A channel will be located by counting down from the particular address code in the Y portion of the E line, one digit for each word, until all 1's are left in the Y portion. Following this, the computer will advance to state #11, and if K5 is false at this time, as previously determined in state #7, the located word in the A line will be recorded in the E and G lines. Otherwise, if K5 is true, the keyboard entry is recorded with a positive sign in E and G. Here, also, the K1 to K4 flip-flops will be set in accordance with the particular preset position of the decimal point switch 210 of FIGS. 1 and 54, preparatory to a print operation. The computer will then advance to the print routine unless the non-print key has been depressed whereupon the computer will advance to the first factor, etc., routine involving states #25 to #32.

State #7

Considering now the case where a computer operation control key has been depressed during the fill routine, resulting in the M flip-flop being set false to cause the

32

computer to advance to state #7, the following operation will occur.

E0—E Recirculate
F0—F Recirculate
G0—G Recirculate
ok5—(E5'B1+E5 B1')Y
m—P2 S1 S2'

Y of $E=0\ 1\ 0\ 1$ if +, -, $\times$, $\div$, 1, D, P0, $<+$, $<-$
10 Propositions have been generated.

Y of $E\neq0\ 1\ 0\ 1$ if S, T, R, Q, 1 ($+-\times\div<+<-P0$), D ($+-\times\div<+<-P0$) A1, A2, A3, A4, A5, A6, A7, A8, A9, A10 (CA+P0+RESET) propositions have been generated.

Since the term 7 is not found in any of the inputs to the recirculate nets of FIGS. 46 to 48, the E Recirculate, F Recirculate and G Recirculate propositions will be generated to effect recirculation of the E, F and G lines.

It will be noted on reference to state #5 that the 0 1 0 1 relation of K1 to K4 was not altered by propositions +, -, $\times$, $\div$, 1, D, P0, $<+$ or $<-$ generated by depression of respective ones of the computer control keys whereas this relation was altered on generation of such propositions as S, T, R, Q, etc.

Accordingly, a comparison is made in state #7 between the Y portion of the E line and the output of flip-flop B1 to set K5 false if the 0 1 0 1 relation has been altered and to leave K5 true if such relation has not been altered.

The term E5'Y generated by a gate in FIG. 51 is applied as an input to a gate 451 (FIG. 38) and is multiplied by B1 and 7 to generate the term ok5. Likewise, the term ok5 is generated by a gate 452 upon reception of the terms E5 Y B1'7, the term E5 Y being generated by one of the gates in FIG. 51.

The computer will remain in state #7 until the P2 Sync point represented by the proposition P2 S1 S2' is passed by the set m net of FIG. 30, whereupon the computer will advance to state #10.

State #10

Upon advancement to state #10, the following operation will occur:

E0—E5 Y' + (M E5' + M'E5)Y
F0—Recirculate
G0—Recirculate
m—Pn
om—E5 Y

50 The above indicates that the Y' portion of the E line is recirculated but that the M flip-flop is utilized to count down, once per word time, the value registered in the Y portion so as to locate the word section in the A line (see FIG. 3) selected by the particular control key which

55 was depressed. That is, considering a condition existing at Pn; when the Y portion of E is to be read, M will be set true at the next pulse time P0 and will be set false immediately thereafter (at P1) if E5=1 at that time, the proposition E5 Y 10 being passed by the om net of FIG. 31. In this case, and at P0, E0 will remain 0, i.e., 1 will be subtracted due to the absence of either of the propositions M E5'Y and M'E5 Y. However, if E5=0 at P0 time, M will remain true throughout the next pulse time

60 P1 and possibly others until a pulse section, P1, P2 or P3 is found wherein E5=1 after which pulse, M will be rendered false. If and when the count has been reduced to where Y of E=1\ 1\ 1, then M will remain true after the Y portion has passed. Accordingly, at the end of a word section, the term Pn M will be generated to advance the program counter to its next state #11.

In order to more clearly understand this operation, an example will now be illustrated. Considering the Y portion of E to represent the address code corresponding to

33

the decimal value 5, and wherein the least significant binary digit is located at the left, such Y portion=1 0 1 0.

	Pn	P0	P1	P2	P3	Y	Y'
(5)	E5-----	1	0	1	0		
	M-----	1	0	0	0		
	E0-----	0	0	1	0		
(4)	E5-----	0	0	1	0		
	M-----	1	1	1	0		
	E0-----	1	1	0	0		
(3)	E5-----	1	1	0	0		
	M-----	1	0	0	0		
	E0-----	0	1	0	0		
(2)	E5-----	0	1	0	0		
	M-----	1	1	0	0		
	E0-----	1	0	0	0		
(1)	E5-----	1	0	0	0		
	M-----	1	0	0	0		
	E0-----	0	0	0	0		
(0)	E5-----	0	0	0	0		
	M-----	1	1	1	1		
	E0-----	1	1	1	1		

As the P_n pulse is registered, M is set true ($M=1$) and since $E5=1$ at this time, none of the gates of the net $E0$ will be open and $E0$ will equal 0. Since $E5 Y=1$, M will be set false at P_1 time and will remain so until reception of the next P_n pulse. Accordingly, the term $M'E5 Y$ will be passed by the $E0$ net to record the binary value 0 0 1 0 equivalent to the decimal value 4 in the Y portion of the E line.

As seen in FIG. 3, since the P_2 Sync mark is located in timed coincidence with a passage of the No. 10 storage accumulator section of the A line past the read head 102, the working accumulator will now be located under the read head and the M flip-flop will again be set true by the P_n pulse.

Now, since at P_0 , $E5=0$ and $M=1$, the term $M'E5 Y$ will pass the net $E0$ to record a 1 in the E line. M will remain true, and since at P_1 , $E5=0$, the term $M'E5 Y$ will again pass the net $E0$ to record 1 in Y of E. At P_2 , however, since $E5=1$, $E0=0$ and M will be set false at P_3 . Accordingly, at P_3 , $E0=0$, leaving the Y portion of the E line equal to 1 1 0 0, equivalent to the decimal value 3.

The above counting down process will continue until Y of $E5=0$ 0 0 0 0. Here, M will not be set false and the first factor accumulator section will be located under the read head. Now, at P_n pulse time, the proposition P_n M will be generated to advance the program counter to state #11 just as the entry accumulator section of the A line passes the read head. In this accumulator is recorded the last amount which was printed and which is available for recall.

State #11

As the computer advances to state #11, the following 55 operation will occur.

E0—K5'A5+K5 E5 Y
F0—Recirculate.
G0—K5'A5+K5 E5 Y'
k1—1-4 DP
k2—1-3 DP
k3—1-2 DP
k4—1 DP
k5—Pn
ok6—Non-print
om—Non-print

Considering for the present a case in which the non-print switch 39 (FIGS. 1 and 59) has been set to non-printing position, the print routine, including states #12 to #24, inclusive, is bypassed. In such case, although information is entered into the G line, and certain of the flip-flops K_1 to K_5 have been set, as required in the print routine, such information will not be used.

34

In any case, however, if K_5 is set false, indicating that a control key, other than one requiring a recall operation, has been depressed, the terms $K5'A5 11$ will be passed by an appropriate gate in the $E0$ net, thereby transferring information from the selected accumulator into the E line. On the other hand, if K_5 has been set true by depression of a control key which requires a recall operation, the keyboard entry contained in the E line is recirculated therein.

- 5 10 At the end of the current word time P_n , K_5 is set true. The term Non-Pr. 11 is passed by product gate 460 of the $ok6$ net, thereby setting K_6 false. Also, the term Non-Pr. 11 is passed by the om net to set M false. Accordingly, the computer will skip, in this case, to the preparatory routine comprising states #25 to #33.

CALCULATION PREPARATORY ROUTINE

After passing directly from the memory look-up routine as a consequence of having set the non-print switch 20 39 to non-print position (or after having passed through the print routine comprising states #12 to #24), the computer advances through the calculation preparatory routine comprising states #25 to #33.

25 Here, information is transferred to the appropriate memory lines, depending on the particular operation and the particular control key depressed. Also, in the event that a multiplication or division operation is to ensue, digital information is shifted to the appropriate denominational position, depending on the setting of the decimal switch.

30 35 If the computer has been set to perform a division or multiplication operation, the computer passes from the preparatory routine at state #32 into either the multiply or divide routine as indicated in FIGS. 15 and 17. Otherwise, it progresses through state #33 to the various add routines to be described later.

State #25

Upon advancing to state #25, the following occurs:

40 45 50 55 60 65 70 75 80 85 90 95
E0—Recirculate
F0—A5 Y'⊕+B1 Y⊗
G0—A5 Y
ok1—Set
k2—K1
ok2—K1'
k3—K2
ok3—K2'
k4—K3
ok4—K3'
k6—0 DP Pn
m—P1 S1 S2'

The above indicates that the E line containing either recalled information or keyboard entered information is recirculated.

If the divide key has been depressed, the Y' portion of the dividend, located in the dividend accumulator section of the A line is recorded in the F line, i.e., the term $A5 Y' ⊕ 25$ is passed by the $F0$ net of FIG. 44, or if the multiply key has been depressed to initiate a multiply operation, the value 1010, i.e. "5", to be utilized for round-off purposes in the multiply routine, is recorded in the Y portion of F.

65 The sign of the value, i.e. 1111 if negative and 0000 if positive, appearing in the Y portion of A is recorded in the G line.

The flip-flops K_1 to K_4 are set false. That is, K_1 is first set false by applying the term 25 to the $ok1$ net. The terms $k1'25$ are passed by the gate 446 of the $ok2$ net. The terms $K2'25$ are generated by the $ok3$ net, etc.

70 75 If the decimal switch has been set at 0, K_6 will be set true at P_n time. For this purpose, the term DP set is generated by the net of FIG. 55 by the proposition 0 DP 25, and such term D Pset, combined with P_n is passed by the $k6$ net (FIG. 39), thus setting K_6 true.

At P1 Sync time (P1 S1 S2') M is set true to advance the computer to state #26.

State #26

Upon advancement to state #26, the first factor (if the latter has been set in the first factor section of the A line preparatory to a multiplication operation) is read. The following operation occurs in this state.

E0—Recirculate
 F0—K4 K6'+F5 K6
 G0—A5 ⊗+G5 ⊕
 k1—F5
 ok1—F5'
 k2—K1
 ok2—K1'
 k3—K2
 ok3—K2'
 k4—K3
 ok4—K3'
 k5—E5[(⊕+<−)'+E5' (⊕+<−)]Y P3
 ok5—P0 Y
 k6—1 DP Pn

The above indicates that the E line is recirculated.

If the multiply key 22 has been depressed to initiate a multiply operation, the first factor, located in the first factor accumulator section of the A line, is transferred to the G line, i.e., the terms A5 ⊗ 26 are passed by the G0 net of FIG. 45. If the divide key has been depressed to initiate a division operation, the sign of the information in the G line is recirculated, the terms G5 ⊕ 26 being passed by the G0 net.

The information in the F line is shifted to the next higher denominational order as determined by the setting of the decimal point switch so that it will be properly located if the division or multiplication operation is to ensue. For this purpose, the F line is effectively lengthened by shifting the information therein through the flip-flops K1 to K4 in the manner noted heretofore.

The output of K4 is entered into the F line if K6 is false at this time, i.e., if the decimal point setting switch has been set to "1" or higher. In such case, the terms K4 K6' 26 are passed by the F0 net.

On the other hand, if K6 has been set true in state #25 as a consequence of the decimal switch having been set to "0", the F line will recirculate, i.e., the proposition F5 F Recirculate will be passed by the F0 net.

In this state, K5 will be set in accordance with the algebraic sign of the information in the E line. That is, it will be set depending on whether or not the minus key 18 or enter-minus key 35 has been depressed. At P3, in the Y portion of the word in the E line, if the sign is 1, indicative of a minus amount and if the minus or enter-minus keys have not been depressed, or if the sign in Y is 0, indicative of a plus amount and if the minus or enter-minus key has been depressed, K5 will be set true, otherwise it will remain false.

K6 will be set true at Pn.

Since M is still true in this state, the computer will advance to state #27 at Pn in the usual manner.

State #27

In state #27, the dividend is recorded in the dividend accumulator if the dividend key is depressed without depressing certain other control keys. The following operation will occur when the computer is in this state.

A0—E5
 A rec.—D (+−×÷<+<−P0)'
 E0—Recirculate
 F0—K4 K6'+F5 K6
 G0—Recirculate

k1—F5
 ok1—F5'
 k2—K1
 ok2—K1'
 k3—K2
 ok3—K2'
 k4—K3
 ok4—K3'
 k5—K5'G5 Y (⊗+⊕) P0
 ok5—K5 G5'Y (⊗+⊕) P0
 k6—2 DP Pn

In this state, A0 is set high in accordance with E5 through the A0 net of FIG. 41.

15 In the event that the dividend key is depressed without depressing the plus, minus, multiply, divide, enter-plus, enter-minus and print only keys (whereupon the terms D (+−×÷<+<−P0)' are generated by the keyboard net of FIG. 57) the term AR will be passed by the net 20 of FIG. 42 and the gates of FIG. 40 will effect recording of the information in the E line into the dividend section of A.

The E and G lines are recirculated.

25 The information in the F line is shifted one denomination higher under control of K6 in the same manner as in state #26, if the decimal point switch has been set to "2" or higher.

If the decimal point switch is set at "2", K6 will be set true at Pn.

30 K5 is set in accordance with the sign appearing in the Y portion of G if a multiply or divide operation is in progress. That is, if Y of G contains 1's, representing a minus sign, and if the multiply or divide key has been depressed, K5 will be set true at P0. In this case, the terms G5 P0 Y (⊕+⊕) 27 will be generated by the k5 net of FIG. 35.

35 On the other hand, if Y of G contains 0's representing a plus sign, and if a multiply or divide operation is in progress, K5 will be set false at P0.

40 Since M is still true, the computer will automatically advance to state #30 at Pn time.

State #30

45 Upon advancing to state #30, the first factor is entered into the first factor accumulator if the first factor key has been depressed without depressing certain other control keys. The following occurs when the computer reaches this state.

A—E5
 AR—1(+−×÷<+<−P0)'
 E0—Recirculate
 F0—K4 K6'+F5 K6
 G0—Recirculate
 k1—F5
 ok1—F5'
 k2—K1
 ok2—K1'
 k3—K2
 ok3—K2'
 k4—K3
 ok4—K3'
 k6—3 DP Pn

The above indicates that in this state, A0 is set high in accordance with the A0 net of FIG. 41.

Here, if the first factor key has been depressed without depressing the plus, minus, multiply, divide, enter-plus, enter-minus or print-only keys, whereupon the terms 70 1 (+−×÷<+<−P0)' are generated by the keyboard net of FIG. 57, AR will be set high. As in the previous state, the term AR will be passed by the net of FIG. 42 and the gates of FIG. 40. Thus, the first factor will be recorded in the first factor accumulator.

The E and G lines are recirculated.

The information in the F line is shifted one denomination higher if the decimal point switch has been set to "3" or higher by shifting such information through K1 to K4 under control of K6.

If the decimal point switch is set "3," K6 will be set true at Pn.

M is still true in this state, so that the computer will advance to state #31, at Pn.

State #31

Upon advancement to state #31, the information in the E line, which at this time may contain a dividend, multiplicand or other factor, is read and entered in the entry accumulator. The following operation will occur.

A0—E5
 AR—rec.
 E0—E5 Y'
 FO—K4 K6'+F5 K6
 G0—Recirculate
 k1—F5
 ok1—F5'
 k2—K1
 ok2—K1'
 k3—K2
 ok3—K2'
 k4—K3
 ok4—K3'
 k6—4 DP Pn

The above indicates that the contents of the E line are recorded in the next accumulator following the first factor accumulator, i.e., the entry accumulator. That is, the terms E5 31 are passed by the A0 net of FIG. 41, and the term 31 is passed by the AR net of FIG. 42, the combined terms A0 AR and their inverts being passed by the gates of FIG. 40 to record on the channel.

The Y' portion of E is recirculated and the entire G line is recirculated.

The information in the F line is again shifted one denomination higher if the decimal point switch has been set to "4" or higher by shifting the same through K1 to K4 under control of K6.

Since M is unchanged, the computer will advance to state #32.

State #32

Upon advancement to state #32, the F line is again shifted to the next higher denomination if the decimal point switch has been set to "5." Also, the G line is shifted to the next lower denomination. The following will occur:

E0—Recirculate
 FO—K4 K6'+F5 K6
 G0—G1
 k1—F5
 ok1—F5'
 k2—K1
 ok2—K1'
 k3—K2
 ok3—K2'
 k4—K3
 ok4—K3'
 ok6—Pn
 om—E5 Y' (×+÷)+Pn

The above indicates that the E line is recirculated.

Information in the F line is shifted to the next higher denominational orders under control of K6 in the same manner as in states #26 to #31. That is, the F line is effectively lengthened by shifting the information therefrom through K1 to K4.

Information in the G line is shifted to the next lower denominational orders and for this purpose the proposition G1 32 is generated by the G0 net. Thus, the recirculating path of the G line is effectively shortened one decimal digit from normal by bypassing flip-flops G2 to G5.

At Pn, K6 is set false.

If a multiplication or division key has been set, M will be set false when E5 Y' occurs, i.e., if the Y' portion of E is not zero, causing the same to skip to either state #63 or #73 of the multiply and divide routines, respectively, depending on which type of operation is to occur. Otherwise the computer will automatically advance in the usual manner to state #33, M being set false at Pn. For this purpose, the propositions E5 Y' (×+÷) 32 and Pn 32 are passed by the om net of FIG. 31.

State #33

Upon advancement to state #33 from state #32, the E line will be recirculated. However, if the computer has skipped to this state from the multiply routine, i.e., from state #71, the product, which would then be recorded in the F line, will be read and transferred into the E line.

The following occurs:

E0—K6 F5+K6'E5
 FO—Recirculate
 G0—Recirculate
 ok1—Set
 k2—K1
 ok2—K1'
 k3—K2
 ok3—K2'
 k4—K3
 ok4—K3'
 ok6—Pn
 m—P2 S1 S2'

The above indicates that the F and G lines are recirculated.

If K6 is false during this state, as occurs when the computer advances from state #32, the terms K6'E5 will not be passed by any of the gates in the E Recirc. net of FIG. 46. Therefore, the term E Recirc. will be high and the proposition E5 E Recir. will be passed by the E0 net to recirculate the E line.

However, if K6 is true during state #33, as occurs when the computer skips from state #71 of the multiply routine to this state, the terms K6 F5 33 will be passed by the E0 net to record the product now appearing in the F line into the E line.

K6 is set false at Pn if it is not already in such condition.

M is set true at P2 Sync time, causing the computer to advance to state #34 of the add routine.

ADD-SUBTRACT ROUTINE

Add and subtract operations are performed in the same routine or groups of routines, i.e., the routines comprising states #34 to #36, #37 to #41 and #54 to #56, depending upon the particular control keys depressed.

The process of addition is carried out by utilizing what is termed the "excess-6" form of addition wherein the binary value of 0 1 1 0, equivalent to the decimal digit 6, is added to each four binary bit group (representing a decimal digit) of either the augend or the addend. In such process, the individual digit sums which involve a carry are found to be correct while those which do not involve a carry are found to be incorrect and must be specially corrected by adding the binary digit 1010, equivalent to the decimal value 10 to such individual sums.

In order to more clearly understand the procedure involved in effecting addition of two multi-digit numbers

utilizing the excess-6 system, the following example is given, representing the following:

354 + 961 = 1315						
(a) Carry	1		1	0		0
(b) Addend	(0) 0 0 0 0	(9) 1 0 0 1	(6) 0 1 1 0	(1) 0 0 0 1		
(c) Correction Factor "6"	(6) 0 1 1 0	(6) 0 1 1 0	(6) 0 1 1 0	(6) 0 1 1 0		
(d) Augend	(0) 0 0 0 0	(3) 0 0 1 1	(5) 0 1 0 1	(4) 0 1 0 0		
(e) Sum (a)+(b)+(c)+(d)	(6) 0 1 1 1	(3) 0 0 1 1	(1) 0 0 0 1	(11) 1 0 1 1		
(f) Correction Factor "10"	(10) 1 0 1 0			(10) 1 0 1 0		
(g) Corrected Sum (e)+(f)	(1) 0 0 0 1	(3) 0 0 1 1	(1) 0 0 0 1	(5) 0 1 0 1		

In the above it will be seen that the units and thousandths denominational orders (counting from the right) do not involve carries, and therefore, the correction factor 1 0 1 0 must be added to obtain the correct total sum.

Subtraction is performed in the present computer by the process of adding the complement of the subtrahend to the true value of the minuend and adding the fugitive 1 to the units denominational order. In those orders where a carry is effected, the true difference value will be found, but in those orders wherein no carry has been effected, the difference will not be correct, and a correction factor of 1010, equivalent to the decimal value 10, must be added.

The following table indicates the process involved in solving an exemplary subtraction problem which is as follows:

0961 - 0354 = 0607						
(a) Carry	1		1	0		
(b) Minuend	(0) 0 0 0 0	(9) 1 0 0 1	(6) 0 1 1 0	(1) 0 0 0 1		
(c) Subtrahend	(0) 0 0 0 0	(3) 0 0 1 1	(5) 0 1 0 1	(4) 0 1 0 0		
(d) Complement of subtrahend	1 1 1 1	1 1 0 0	1 0 1 0	1 0 1 1		
(e) (a)+(b)+(d)	0 0 0 0	0 1 1 0	0 0 0 0	0 1 0 0		
(f) Fugitive 1				0 0 0 1		
(g) Correction Factor "10"				1 0 1 0		
(h) Difference (e)+(f)+(g)	(0) 0 0 0 0	(6) 0 1 1 0	(0) 0 0 0 0	(7) 0 1 1 1		

In the above example it will be noted that the addition of the complement of the subtrahend to the minuend will result in correct digital values for the three highermost denominations since a carry has been effected therein. However, the digital values resulting in the lowermost order will be found to be erroneous, since no carry was effected therein, thus requiring the addition of the amount 1010 to the fugitive 1 and the sum of the minuend and complement of the subtrahend to obtain the proper digit difference of 0111. The carry resulting from the latter process is disregarded.

State #34

In this state the signs and relative magnitudes of the two numbers to be added are compared, preparatory to the actual addition operation.

The following occurs:

E0—Recirculate
F0—A5
G0—E5
k1—(K5 A5' + K5'A5) Y 34
k3—A5 E5' Y'
ok3—A5'E5 Y'

The above indicates that the E line, having one of the numbers to be added, is recirculated.

Since the computer is advanced to this state upon passage of the P2 Sync point in the sync track past the read head, the working accumulator having therein the second number to be added will now pass under the read head and the information therein will be recorded in the F line.

Information in the E line will be recorded in the G line.

K1 is set in accordance with the algebraic signs of the two numbers. If the signs are the same, K1 is set to "0" and if they are different, K1 is set to "1." In this regard, it will be recalled that K5 was set true in state #27 if the

effective sign of the number in the G line is positive or was set false if such sign is negative. Accordingly, if the

sign of the amount in the working accumulator WA indicates a negative member, i.e. if the terms A5'Y are high, the proposition K5 A5'Y 34 is passed by the k1 net to set K1 true.

Correspondingly, if K5 is false and sign of A is positive, the proposition K5'A5 Y 34 is also passed by the k1 net.

20 K3 is set to indicate the relative magnitudes of the two numbers. That is, if the number in A is greater than E, K3 is set true, but if A is less than or equal to E, K3 is set false. In the first case, the terms A5 E5'Y'34, indicative of the fact that A is greater than E, will be passed by the k3 net, whereas in the latter case, the terms A5'E5 Y'34 will be passed by the ok3 net. At Pn the computer will advance to state #35.

25

State #35

In this state, the constant 0110 is added in accordance with the aforementioned "excess 6" system if the signs of the two numbers are the same, indicative of an addition operation. If the signs of such numbers being added are different, indicative of a subtraction operation, the smaller number is complemented in preparation for addition.

45 The operation is as follows:

E0—Recirculate
F0—(B2'F5'K2' + B2 F5 K2' + B2 F5'K2 + B2'F5 K2)
Y'K1 + F5 Y K1' + F5'K3'K1 + F5 K3 K1
G0—G5'K1 K3 + G5 K1' + G5 K3'
k2—B2'F5 Y'
ok2—B2 F5'Y'
k3—Pn

50

The above indicates that the E line is recirculated.

The value 0110 is added and the sign of the two numbers is retained if such signs are the same. If the signs are different and F is smaller than G, F is complemented and the complement added to G. If the signs are different and F is larger than G, F is recirculated. That is, if K1=0, indicating that the signs are the same, the value 0110 is added to the amount in the Y' portion of F. Here, the pulse counter flip-flop B2 is used to provide the value 0110, the latter being obtained from the B2' output so as to complement the normal 1001 output.

60 65 K2 is set in accordance with the carry resulting from the addition of 0110 to F. If a carry is effected from such addition, K2 is set true, i.e. the terms 35 B2'F5 Y' are passed by the k2 net. If such carry is not effected, the terms B2 F5'Y'K2 35 are passed by the ok2 net.

According to the well known principle of binary addition and considering two numbers A and B and any carry K involved, the sum of such addition will be equal to "1" under the following conditions. A' B'K' or A'B' K' or A' B'K or A B K. By substituting B2' and F5 for A and B, respectively, and K2 for the carry, and entering the

70

41

same in F, we have the equation $F0 = (B2'F5'K2' + B2F5K2' + B2F5'K2 + B2'F5K2) Y'K1'$. Such proposition is generated by the $\Sigma 6$ net of FIG. 53 and the terms $\Sigma 6$, 35 are passed by the $F0$ net of FIG. 44.

Since, when both signs are the same, such sign is retained (as it is the sign of the result) and the terms $F5YK1'$ are generated by the $\Sigma 6$ net and passed by the $F0$ net.

If the signs of the two numbers are different, indicating a subtract operation, and if the number in F is smaller than in G, the terms $F5'K3'K1$ will be passed by the $\Sigma 6$ and $F0$ nets. If G is smaller than F and the signs are different, the F line will be recirculated, i.e. the terms $F5K3K1$ will be passed by the $\Sigma 6$ and $F0$ nets. In both cases, the Y portion of F contains the correct sign of the result.

If the signs are different and F is greater than G, the terms $G5'K1K3$ will be passed by the $G0$ net to complement the number in G. Otherwise, G is unchanged, i.e., if the signs are the same, regardless of the relative magnitudes, the terms $G1K1'$ will be passed by the G recirculate net of FIG. 48 and the $G0$ net of FIG. 45 to recirculate the G line. If the terms $G5K3'$ are passed, indicating that G is greater than F, the G line will be recirculated, (the above is $G5(K1'+K3') = G5(K1K3')$).

At P_n , $K3$ is set to "1" and the computer advances to state #36, which will control the proper sign (Y time) of the final result.

State #36

30

In this state the final addition is carried out. The F and G lines are added, and one digit time later the "Fix-up" addition is performed where necessary, and this total sum is recorded in the working accumulator.

The operation is as follows:

$$A0 - E5 T(\oplus + \ominus + \otimes + \ominus) + [K3 F5 + K3'(F5 B1 K4' + F5' B1' K4' + F5' B1 K4 + F5 B1' K4)] T'(\oplus + \ominus + \otimes + \ominus) \quad 40$$

A Rec.— $T + \oplus + \ominus + \otimes + \ominus$

E0—Recirculate

F0—Blank

f2— $F1G1'K1' + F1'G1K1' + F1'G1'K1 + F1G1K1$

G0—Blank

k1— $F1G1$

ok1— $F1'G1'$

k3— $K1P0Y'$

ok3— $K1'P0Y'$

k4— $P0-2F5B1' = F5P1$

ok4— $F5' B1 + P3$

The above indicates that $K1$ is set true if a binary carry is to occur as a result of addition of the F and G binary bits during Y'. The binary sum of F and G controls $F2$. $F2 = "1"$ when the sum of the individual binary digits equals 1. For this purpose, the proposition $F1G1'K1' + F1'G1K1' + F1'G1'K1 + F1G1K1$ is generated by the ΣFG net of FIG. 50 and passed by the $f2$ net of FIG. 49.

$K3$ is set true by $K1$ at the beginning of each digit time ($P0$) where a carry is indicated from the $P3$ pulse time of the previous digit. $K3'$, therefore, indicates that a "fix-up" addition must be made. During Y, $K3$ is invariably true thereby retaining the correct sign in F.

$K4$ is set true if a carry is indicated during the "fix-up" addition (addition of the value 1010). This latter value is obtained from the $E1$ flip-flop of the pulse counter, the false output being used to obtain the value 1010.

In the "fix-up" addition, should there be a carry from the last column, i.e., $P3$ pulse time, it is disregarded; therefore, to prevent such a carry from being put into the sum, $K4$ is set false in state #36 by the $P3$ pulse.

As previously noted, the sum of the F and G lines is

42

applied to the $F2$ flip-flop. Therefore, it must necessarily be transferred through the $F2$, $F3$, $F4$ and $F5$ flip-flops, thereby effecting a delay of four pulse times or one digit. This delay is effective to allow the "fix-up" addition to be performed simultaneously with the addition of the F and G lines.

The F and G lines are blanked to insure that the Y information will be zero.

At this time the working accumulator passes under the record head to record the final sum therein. That is, the proposition

$$[K3 F5 + K3' (F5 B1 K4' + F5' B1' K4' + F5' B1 K4 + F5 B1' K4)] \quad 15$$

is generated by the $\Sigma 6$ net of FIG. 52 and is combined with the proposition

$$36 T'(\oplus + \ominus + \otimes + \ominus)$$

of the $A0$ net (FIG. 41). Also, the proposition

$$E5 T(\oplus + \ominus + \otimes + \ominus) \quad 36$$

is passed by the $A0$ net. The proposition

$$T + (\oplus + \ominus + \otimes + \ominus) \quad 36$$

is passed by the AR net of FIG. 42. This gates a record-ing if the total, plus, minus, multiply or divide key has been depressed. In the case of depression of the total key, zeros are recorded.

At P_n the computer advances to state #37.

State #37

In this state, the signs and relative magnitudes of the numbers to be added are entered into the storage accumulator $A1$ and compared, preparatory to the actual addition operation.

The following occurs:

E0—Recirculate
F0—A5
G0—E5
k1— $(K5 A5 + K5' A5) Y$
k3— $A5 E5' Y'$
ok3— $A5' E5 Y'$

As will be seen from above, the computer, while in this state, functions in precisely the same manner as when in state #34. However, at this time, the first storage accumulator (A1) passes under the read head 102 to read the amount therein and to enter the same into the F line.

At P_n the computer advances to state #40.

State #40

In this state the constant 0110 is added to the numbers being added in accordance with the "excess 6" system and in precisely the same manner as in state #35.

The operation is as follows:

E0—Recirculate
F0— $(B2'F5'K2' + B2F5K2' + B2F5'K2 + B2'F5K2) Y'K1' + F5YK1' + F5'K3'K1 + F5K3K1$
G0— $G5'K1K3 + G5K1' + G5K3'$
k2— $B2'F5Y'$
ok2— $B2F5'Y'$
k3— P_n

As indicated, the computer, while in this state, functions in the same manner as in state #35.

At P_n the computer advances to state #41.

State #41

In this state the final addition is carried out in a manner similar to the operation performed in state #36, except that the storage accumulator $A1$ is blanked for a clear A operation.

43

The operation is as follows:

A0-[K3 F5+K3'(F5 B1 K4+F5'B1'K4'+F5'B1K4+F5 B1'K4)](CA)'
 A rec.-(A1+t T)(RESET)'(P0)'
 E0—Recirculate
 F0—Blank
 f2—F1 G1'K1'+F1'G1K1'+F1'G1'K1+F1 G1 K1
 G0—Blank
 k1—F1 G1
 ok1—F1'G1'
 k3—K1 P0 Y'
 ok3—K1'P0Y'
 k4—P0-2 F5 B1'=F5 P1
 ok4—F5' B1+P3

The proposition

[K3 F5+K3'(F5B1 K4'+F5'B1'K4'+F5'B1K4+F5B1'K4)]

is generated by the Σ -6 net of FIG. 53 and this is combined with the proposition (CA)' 41 of the A0 net of FIG. 41.

The proposition (A1+t T)(RESET)'(P0)' is generated by the AR net of FIG. 42 to record the same. This gates a recording during this state if the A1 key is down or if the automatic $T-t$ condition exists as long as they are not accompanied by a reset or print-only operation. If A1 is to be cleared (total operation for A1) A0 will be entirely zero by virtue of the (CA)' proposition.

At Pn the computer advances to state #42.

State #42

In this state, the amount in the entry section of the accumulator is recalled and read into the E line. If the A2 selection key has been depressed or the switch 40 (FIGS. 1 and 61) has been set to automatically accumulate second factors or products in the A2 section (when a multiply operation is performed), the computer will skip to state #54 for addition.

The operation is as follows:

E0—A5 (Recirculate of Prod. Acc.)
 F0—Recirculate
 G0—Recirculate
 k5—[A5(θ+⊖)'+A5'(θ+⊖)]Y P3
 (out of Prod. Acc.)
 ok5—P0 Y (out of Prod. Acc.)
 om—(A2+m ⊖)'(RESET)'(P0)'

A switch controls whether or not the product is replaced by the second factor for multiplying.

From the above, it will be noted that the terms A5 42 are passed by the E0 net to read the recalled amount and enter the same in the E line.

K5 is set true at Y P3 in accordance with the sign A5 if the minus or enter-minus has not been depressed. Otherwise, it is set false.

If the A2 selection key has been depressed, or the accumulator switch 40 has been set to automatically accumulate products or second factors in A2, the proposition (A2+m ⊖)'(P0)' is generated by the 42 skip net of FIG. 21 and applied to the om net of FIG. 31. Accordingly, the counter, in such case, will skip to state #54. Otherwise, at Pn the counter will automatically advance to state #43.

State #43

Upon advancement to state #43, the computer will be conditioned to read an amount registered in the A3 accumulator if the A3 selection key has been depressed. The following will occur:

E0—Recirculate
 F0—Recirculate
 G0—Recirculate
 om—A3 (RESET)'(P0)'

44

The above indicates that the E, F and G lines are recirculated and if the A3 selection key has been depressed without concurrently depressing the reset and print-only keys, the terms A3 (RESET)'(P0)' will be generated by the state #43 gate of FIG. 21, and passed by the om net of FIG. 31 to advance the computer to state #54. Otherwise the computer will automatically advance to state #44.

State #44

Upon advancement to state #44, the computer will be conditioned to read an amount registered in the A4 accumulator if the A4 selection key has been depressed. The following will occur:

E0—Recirculate
 F0—Recirculate
 G0—Recirculate
 om—A4 (RESET)'(P0)'

The above operation is similar to that of state #43 except that the computer will skip to state #54 upon depression of the A4 selection key in the absence of depression of the reset and print-only keys, the terms A4 (RESET)'(P0)' being generated by the state #44 gate. Otherwise, the computer will advance to state #45.

State #45

Upon advancement to state #45, the computer will be conditioned to read an amount registered in the A5 accumulator if the A5 selection key has been depressed. The following will occur:

E0—Recirculate
 F0—Recirculate
 G0—Recirculate
 om—A5 (RESET)'(P0)'

The above operation is similar to that of state #44 except that the computer will skip to state #54 upon depression of the A5 selection key in the absence of depression of the reset and print-only keys. In this case, the terms A5 (RESET)'(P0)' is generated by the state #45 gate. Otherwise, the computer will advance to state #46.

State #46

Upon advancement to state #46, the computer will be conditioned to read an amount registered in the A6 accumulator if the A6 selection key has been depressed in the absence of depression of the reset and print-only keys. The following will occur:

E0—Recirculate
 F0—Recirculate
 G0—Recirculate
 om—A6 (RESET)'(P0)'

The above operation is similar to that of state #45 except that the computer will skip to state #54 upon depression of the A6 selection key in the absence of depression of the reset and print-only keys. In this case, the terms A6 (RESET)'(P0)' is generated by the state #46 gate. Otherwise, the computer will advance to state #47.

State #47

Upon advancement to state #47, the computer will be conditioned to read an amount registered in the A7 accumulator if the A7 selection key has been depressed. The following will occur:

E0—Recirculate
 F0—Recirculate
 G0—Recirculate
 om—A7 (RESET)'(P0)'

The above operation is similar to that of state #46 except that the computer will skip to state #54 upon depression of the A7 selection key in the absence of depression of the reset and print-only keys. The terms

45

A7 (RESET)' (P0)' is generated by the state #47 gate. Otherwise, the computer will advance to state #50.

State #50

Upon advancement to state #50, the computer will be conditioned to read an amount registered in the A8 accumulator, if the A8 selection key has been depressed. The following will occur:

E0—Recirculate
F0—Recirculate
G0—Recirculate
om—A8 (RESET)' (P0)'

10

The above operation is similar to that of state #47 except that the computer will skip to state #54 upon depression of the A8 selection key in the absence of depression of the reset and print-only keys. The terms A8 (RESET)' (P0)' is generated by the state #50 gate. Otherwise, the computer will advance to state #51.

15

State #51

Upon advancement to state #51, the computer will be conditioned to read an amount registered in the A9 accumulator if the A9 selection key has been depressed. The following will occur:

E0—Recirculate
F0—Recirculate
G0—Recirculate
om—A9 (RESET)' (P0)'

20

The above operation is similar to that of state #50 except that the computer will skip to state #54 upon depression of the A9 selection key in the absence of depression of the reset and print-only keys, the terms A9 (RESET)' (P0)' being generated by the state #51 gate. Otherwise, the computer will advance to state #52.

25

State #52

Upon advancement to state #52, the computer will be conditioned to read an amount registered in the A10 accumulator if the A10 selection key has been depressed. The following will occur:

30

E0—Recirculate
F0—Recirculate
G0—Recirculate
om—A10 (RESET)' (P0)'

35

The above operation is similar to that of state #51 except that the computer will skip to state #54 upon depression of the A10 selection key in the absence of depression of the reset and print-only keys, the terms A10 (RESET)' (P0)' being generated by the state #52 gate. Otherwise, the computer will advance to state #53.

40

State #53

Upon advancement to state #53 as will occur if none of the accumulator selection keys has been depressed, the computer will automatically skip back to the post state #3. The following will occur:

45

E0—Recirculate
F0—Recirculate
G0—Recirculate
om—Set

50

The term 53 will cause the om net to set M false, whereupon the computer will return to state #3.

55

ADD TO A2 TO A10 ROUTINE

After selection of a particular storage accumulator by depression of one of the selection keys A2 or A10, the computer will skip to the "Add to A2 to A10" routine comprising states #54 to #56, where the selected accumulator is read and the information entered in the F line.

The actual process of addition is similar to that per-

46

formed in the previously described add routines occurring in states #34 to #36 and #37 to #41.

State #54

Upon advancement to state #54 from any of the accumulator selecting states #42 to #52, the following operation will occur:

E0—Recirculate
F0—A5
G0—E5
k1—(K5 A5'+K5'A5) Y
k3—A5 E5'Y'
ok3—A5'E5 Y'
m—Set

15

The above indicates that the procedure followed is similar to that in states #34 and #37. The E line is recirculated and information therein is read and recorded in the G line. Information in the selected storage accumulator is read and recorded in the F line.

20

K1 is set in accordance with the algebraic sign of the numbers in the selected storage accumulator and the G line.

25

It will be recalled that K5 was set in state #42 in accordance with the sign of A5. Such setting is still retained and used to properly set K1.

K3 is set to indicate the relative magnitudes of the two numbers, being set true if A is greater than E and set false if A is less than or equal to E.

M is set true by the term 54 and accordingly at Pn the computer automatically advances to state #55.

State #55

Upon advancement to state #55 the same procedure is followed as in state #35. Here, 6's are added to the information in the F line if an addition is to be performed. Otherwise, when a subtraction is to be performed, the smaller number is complemented and is then added to the larger number. The operation is as follows:

E0—Recirculate
F0—(B2'F5'K2'+B2 F5 K2'+B2 F5'K2+B2'F5 K2)
Y'K1'+F5 Y K1'+F5'K3'K1+F5 K3 K1
G0—G5'K1 K3+G5 K1'+G5 K3'
k2—B2'F5 Y'K1'
ok2—B2 F5'Y'K1'
k3—Pn

30

The above indicates that the value 0110 obtained from B2 is added to the Y' portion of F if K1=0, i.e., if the signs are the same indicative of an add operation. If the signs are different and F is smaller, F will be complemented and added. If the signs are different and G is smaller, G will be complemented and added.

35

K2 will be set true if a carry is effected in adding 0110 to the information in the F line. K3 is set to 1 at Pn to control the correct sign in F.

State #56

In this state the final addition is carried out as follows:

A0—[K3 F5+K3'(F5 B1 K1'+F5'B1'K4'+F5'B1 K4+F5 B1'K4)] (CA)'

A rec.—56

F0—Blank
F2—F1 G1'K1'+F1'G1 K1'+F1'G1'K1+F1 G1 K1
G0—Blank
k1—F1 G1
ok1—F1'G1'
k3—K1 P6 Y'
ok3—K1'P6 Y'
k4—P0-2 F5 B1'=F5 P1
ok4—F5'B1+P3
om—Set

75

The above indicates that K1 is set true if a binary carry is to occur as a result of addition of the information in the F and G lines.

K3 controls the fix-up addition.

K4 is set true in accordance with the carry for the fix-up or corrective addition.

The decimal sum of F and G is recorded in A for accumulation.

M is set false by the state term 56 whereby the computer skips back to the post state #3.

MULTIPLY ROUTINE

The multiply routine comprises a series of addition operations combined with shifting of the first factor relative to the progressing accumulation. The second factor is shifted so that the digit related to the addition in process controls the number of additions. The first factor registered in the G line is shifted to the left and the second factor registered in the E line is shifted to the right as an incident to each addition operation.

The various partial products are accumulated in the F line until the final product is registered.

In the machine of the present invention, a preset fixed decimal point is used. In multiplying numbers including decimals, the number of decimal places to the right of the decimal point in the product is equal to the sum of the number of places in the first and second factors. Accordingly, a round-off feature is provided to round off the decimal value in the product, to the right of the decimal point, to a number of decimal places equal to the number of decimal places in the first and second factors. This is accomplished by adding the value 5 to the order to the right of the capacity or to the right of the last digit in the product which will be printed. This will round off the product to the proper decimal point capacity. If a zero decimal point position exists, this round off is absent.

The value 0101 equivalent to the decimal value 5, used for round off, is obtained from the counter B2 and is added to the F line.

State #63

The computer skips to this state from state #32 in the event the multiply key has been depressed to initiate a multiply operation as was noted in connection with state #32.

In state #63, the contents of the E line and the F line containing the second factor and product, respectively, are interchanged. The first factor now contained in the G line is delayed or shifted leftward one denominational order bypassing the same through the K1 to K4 flip-flops. It will be recalled that the G line was pre-shifted in reverse or to the right in state #32 to account for this first shift.

The operation is as follows:

E0—F5
F0—E5
G0—K4
k1—G5
ok1—G5'
k2—K1
ok2—K1'
k3—K2
ok3—K2'
k4—K3
ok4—K3'
m—Set

The above indicates that the output of the F5 flip-flop controls the input to the E line and the output of the E5 flip-flop controls the input to the F line. The output of the G5 flip-flop controls the K1 flip-flop and the information thus translated is shifted in succession through

the K2, K3 and K4 flip-flops, thereby delaying this information by one denominational digit, which in effect, shifts the multiplicand one denominational order to the left.

5 M is set true by the state term 63, causing the computer to advance to state #64 at Pn.

State #64

10 In this state, the contents of the E and F lines are interchanged while shifting the second factor one denominational order to the right.

If a non-zero digit exists anywhere in the second factor, the computer will skip back to state #62, otherwise it will advance to state #65.

15 The operation is as follows:

E0—F1
F0—E5
G0—Recirculate
m—Pn
om—F1

The above indicates that the output F1 is connected to the input of the E line, thereby shifting the second factor one denominational order to the right.

25 The output E5 is connected to the input of the F line, thereby returning the E and F lines to their status earlier existing in which the E line contained the second factor and the F line contained the partial product, but wherein the E line has been shifted one order to the right. It has been prearranged that Y of F is 0000 as this will be shifted to the most significant digit position of E. However, the net effect is that E shifts to the right.

30 35 If the second factor has contained a significant digit, the terms 64 F1 will be passed by the om net to cause the computer to skip back to state #62.

If the second factor, controlling the digit by digit process (shifting and subtracting), has been reduced to all zeros, the program counter will count to state #65. That is, the terms F1 64 will not be generated by the om net and M will remain true in state #64.

State #62

40 In this state, the digit 1 is subtracted from the Y portion of the E line containing the second factor, using the term M as a carry. If the decimal digit now in the Y portion of the E line is not "0," M will be set false, causing the computer to skip back to state #60, otherwise the program counter by virtue of M=1 will advance to state #63.

45 The K1 to K4 flip-flops will be set false.

The operation is as follows:

E0—E5 Y+(M E5'+M'E5) Y
F0—Recirculate
G0—Recirculate
ok1—Set
k2—K1
ok2—K1'
k3—K2
ok3—K2'
k4—K3
ok4—K3'
om—E5 Y

50 55 60 65 The above indicates that Y' portion of the E line is recirculated, but the M flip-flop is utilized to subtract one from Y once per word time in this state. Here, if M is true, i.e. if M=1, the digits in Y of E are complemented, but if M=0 these digits are unchanged. That is, if M is true, as occurs when the computer has advanced to state #62 from state #61, and a digit in Y' of E is false, the corresponding digit of E0 will be set true, or if M is false as occurs when the computer has skipped to state #62 from state #64 and E5 is true, E0 will be set true.

49

This subtraction occurs in substantially the same manner as described in connection with state #10.

The K1 to K4 flip-flops will be set false in the same manner as described in connection with state #25.

State #60

The computer skips to this state from state #62 when the Y portion of E has not been reduced to zero. Here, the constant 0110 is added to the amount in the F line 10 in accordance with the "excess 6" system.

The operation is as follows:

E0—Recirculate
 F0— $(B2'F5'K2' + B2 F5 K2' + B2 F5'K2 + B2'F5 K2)$
 $Y'K1' + F5 Y K1' + F5'K3'K1 + F5 K3 K1'$
 G0— $G5'K1 K3 + G5 K1' + G5 K3'$
 k2— $B2'F5 Y'$
 ok2— $B2 F5' Y'$
 k3—Pn
 m—Set

The above operation is similar to that performed in state #35.

At Pn, the computer will automatically advance to state #61. 25

State #61

In this state, the contents of the G line containing the first factor are added to the partial product in the F line.

The operation is as follows:

E0—Recirculate
 F0— $K3 F5 + K3'(F5 B1 K4' + F5 B1'K4 + F5' B1 K4 + F5 B1 K4)$
 f2— $F1 G1' K1 + F1' G1 K1' + F1' G1' K1 + F1 G1 K1$
 G0—Recirculate
 k1—F1 G1
 ok1—F1' G1'
 k3—K1 P0 Y'
 ok3—K1' P0 Y'
 k4— $P0 - 2 F5 B1' = F5 P1$
 ok4— $F5' B1 + P3$

The above operation is similar to that performed in state #36 in finally adding the first factor to the corrected partial product in the F line. However, K6 is set true at Pn if the decimal point switch has been set at 0.

Since M was set true at state #60, the computer will now automatically advance to state #62 where the aforementioned processing will continue. 50

State #65

Upon advancement to this state from state #64 after completion of the accumulation of the product, the partial product in the F line is shifted to the right, once for each word time in accordance with the setting of the decimal point switch. 55

The following operation will occur:

E0—Recirculate
 F0— $K6'F1 Y' + K6 F5$
 G0—Recirculate
 k6—1 DP Pn

The above indicates that the F line is shifted to the left if K6 had been set false in state #62 by virtue of the decimal point switch being set at 1 or higher. If, however, the decimal point switch has been set to 0, K6 is set false and F recirculates, the product being in its proper position relative to the decimal point. 70

K6 is set true at Pn if the decimal point switch has been set to 1.

50

State #66

Upon advancing to this state, the partial product in the F line is again shifted to the right if K6 is false or is recirculated if K6 is true.

The following operation occurs:

E0—Recirculate
 F0— $K6'F1 Y' + K6 F5$
 G0—Recirculate
 k6—2 DP Pn

The above operation is similar to that performed in state #65 except that K6 is set true at Pn if the decimal point switch has been set to 2.

Had the decimal point switch been set to 1 or 0, the F line will be properly positioned at this point. 15

State #67

Upon advancing to this state, the partial product in the F line is again shifted to the right one denominational order if K6 is false or is recirculated if K6 is true. 20

The following operation occurs:

E0—Recirculate
 F0— $K6'F1 Y' + K6 F5$
 G0—Recirculate
 k6—3 DP Pn

The above operation is similar to that of state #66 except that K6 is set true at Pn if the decimal point switch has been set to 3. Had the decimal point switch been set to 0, 1 or 2, the F line will be properly positioned at this point. 30

State #70

Upon advancing to this state, the partial product in the F line is again shifted to the right if K6 is false or it is recirculated if K6 is true. 35

The operation is as follows:

E0—Recirculate
 F0— $K6'F1 Y' + K6 F5 Y'$
 G0—Recirculate
 k6—4 DP Pn

The above operation is similar to that occurring in state #67 except that K6 is set true at Pn if the decimal point switch has been set to 4. Had the decimal point switch been set to 0, 1, 2 or 3, the F line will be properly positioned at this point. 45

State #71

Upon advancing to this state, the partial product in the F line is again shifted to the right if K6 is false or is recirculated if K6 is true. 50

The operation is as follows:

E0—Recirculate
 F0— $K6 F1 Y' + K6 F5$
 G0—Recirculate
 k6—Pn
 om—Set

The above operation is similar to that performed in state #70 except that K6 is invariably set true by Pn. M is set false by the state term 71 whereupon the computer will skip to state #33. 65

The F line now has accounted for all proper settings of the decimal point, and the product is properly set relative to the decimal point and word structure. 70

DIVIDE ROUTINE

The divide routine comprises a combination of shifting and subtracting operations in which the divisor is first shifted to proper position relative to the already properly positioned dividend, i.e. until the divisor is positioned so 75

that it is of greater magnitude than the dividend. The divisor undergoes a process where it is shifted and subtracted from the dividend until it becomes larger than the value of the dividend. At such time, by virtue of the value comparing process, the subtractive process is arrested and the divisor is again shifted to the right relative to the dividend and the process repeated.

The number of operations, i.e., the number of digits in the quotient, is determined by the initial shifting of the divisor which has been accounted for by marker pulses. These, when removed by the successive shifts, indicate termination of the routine.

State #73

The computer is advanced to state #73 from state #32 as an incident to depression of the division key. It will be recalled that in state #32 the F line, which contains the dividend in case of a division operation, was located in the proper denominational position relative to the decimal point as a consequence of having passed through states #27, #30, #31 and #32. In this state #73, the divisor contained in the E line is shifted to the left and the G line concurrently shifted to the right. The P_n pulse is recorded in the most significant digit position in the G line for each word time to form markers indicating the number of digit shifts performed on the divisor and consequently will also be the number of digits (zeros included) that will be acquired by the quotient in this process. The value of the divisor is continuously compared with the value of the dividend and when the divisor becomes greater than the dividend by virtue of such shifting operation, the computer will be advanced to the next state #74.

The operation is as follows:

E0—K4 (BS)'
F0—Recirculate
G0—G1+ P_n
k1—E5
ok1—E5'
k2—K1
ok2—K1'
k3—K2
ok3—K2'
k4—K3
ok4—K3'
m—F5'K4
om—F5 K4'

The above indicates that the E line is shifted left once per word time by shifting the information therein through the K1 to K4 flip-flops in the absence of a backspace operation. For this purpose, the terms E5 73 are passed by the k1 net and the terms K4 (BS)' 73 are passed by the E0 net. (BS)' is ineffective here since backspace will not occur during a divide operation. However, it is carried along as a circuit signification.

The G line is shifted right, once per word time, by passage of the terms G1 73 by the E0 net. Also, the P_n pulses are recorded to indicate the position markers by passage of the terms P_n 73 by the G0 net. Since G is initially blank, a series of pulses at P3 (recorded at P_n) will shift right from the most significant digit end of the line.

The output of F5 is continually compared with the output of K4, which is E shifted, to indicate when the divisor becomes greater in value than the dividend and for this purpose the terms F5' K4 are passed by the set m net and the terms F5 K4' are passed by the om net.

In the event M is set false, the computer is merely retained in this state to again follow the above process, but if set true, the computer will advance to state #74.

State #74

Upon advancing to state #74 the P_n markers, previously recorded in the G line, are recorded in the E line to indicate the number of digits in the quotient. The F line is recirculated and the divisor in the E line is complemented and entered into the G line.

The operation is as follows:

10 E0—G5
F0—Recirculate
G0—E5'

The above indicates that the output of G5 is entered into the E line.

15 The terms E5' 74 are passed by the G0 net, thus complementing the divisor.

Since the computer entered the state #74 only as a consequence of M being set true, the computer will automatically advance to state #75.

20

State #75

Upon advancement to this state, the dividend and divisor are recirculated in the G and F lines, respectively. The complement of the Y' portion of the divisor which is the true divisor, previously complemented, is compared with the Y' portion of the dividend and if the latter is greater, the computer will advance to state #76 for a decimal addition (actually a subtraction). However, if otherwise, the computer will skip to state #77 preparatory to a shifting operation in that state. If under this condition there is an absence of a marker pulse in E at P_n , M will be set true on entering #77 which is the condition for exit from the routine.

30

The operation is as follows:

35 E0—Recirculate
F0—Recirculate
G0—Recirculate
k1—Pn M
ok1—Pn M'
k3—Pn M
ok3—Pn M'
m—Y+G5 F5 Y'+ P_n E5'
om—G5'F5'Y'

The above indicates that the E, F and G lines are recirculated.

The terms Y+G5 F5 Y'+ P_n E5' are passed by the set m net indicating that F is equal to or greater than G or indicating that the last marker pulse has been exhausted from the G line. Also, if M is set true, K1 and K3 are set equal to "1" at P_n time to eventually cause a decimal addition in state #76. If M is set false by passing through the terms G5'F5'Y' in the om net, K1 and K3 are set equal to "0" preparatory to a shift operation in state #77.

State #76

60 Upon entry into this state from state #75, the current quotient digit being determined (in Y of E) is increased by one. The subtraction is carried out by decimal addition the complements in G to F. This operation is similar to the subtraction of G from F as done in states #36, #41 and #56. The remainder resulting from this operation is recorded in F. The K flip-flops used here will be used in the same manner as in states #36, #41 and #56.

65 Since M is used as the binary carry for the addition in E at Y time, it will be set to zero (although a binary addition) for no digit of the quotient will ever result greater than 9. M has been preset to 1 at state #75 which effects an add-one operation. Since M is set equal to zero, the computer will skip back to state #75.

70

53

The operation is as follows:

E0—E5 Y' + (M E5' + M'E5) Y
 F0—K3 F5 + K3' (F5 B1 K4' + F5'B1' K4' + F5'B1 K4
 + F5 B1' K4)
 f2—F1 G1' K1' + F1' G1' K1 + F1 G1' K1 + F1 G1 K1
 G0—Recirculate
 k1—F1 G1
 ok1—F1' G1'
 k3—P0 K1 Y'
 ok3—P0 K1' Y'
 k4—(P0-2) F5 B1' + F5 B1
 ok4—F5'B1 + P3
 om—E5' Y

The above indicates that a similar procedure is followed in building up the quotient in the E line as was done in connection with the subtraction in state #10.

The addition in the F line is carried out in the same manner as the addition previously entered into the A line in state #76.

K1 is set true if a binary carry is to occur as a result of addition of F and G binary bit. During Y', K3 is set true by K1 at the beginning of the next digit time to obtain the decimal carry indication of K1.

K4 is set in accordance with the carry for the corrective addition, i.e., addition of the value 1010. Use is made of the B1 flip-flop as a pulse counter, the output B1' being used to obtain the complement of the value 0101.

State #77

Upon entrance into this state from state #75, the quotient in E is shifted left. The remainder in the F line is recirculated and the divisor is shifted to the right, and the division is continued. However, when the division is complete, the computer will advance to state #0. The last shift of the quotient will then have the numerical result set to its proper position.

The operation is as follows:

E0—K4 (BS)'
 F0—Recirculate
 G0—G1
 k1—E5
 ok1—E5'
 k2—K1
 ok2—K1'
 k3—K2
 ok3—K2'
 k4—K3
 ok4—K3'
 om—Pn

The above indicates that the E line containing the quotient is shifted to the left by shifting the output thereof through the K1 to K4 flip-flops.

The G line is shifted to the right by connecting the output of G1 to the input of G.

If division is completed at this stage, M will have been set equal to 1, causing the machine to progress to state #0, otherwise, M=0 and the computer will skip back to state #75 to continue the division operation.

State #0

In this state, the sign of the quotient is registered in the Y portion of the quotient located in the E line and also in the Y portion of the remainder located in the F line.

The operation is as follows:

F0—F5 Y' + K5 Y
 F0—F5 Y' + K5' Y
 G0—Recirculate
 m—P0 S1 S2' (P0 Sync)

The above indicates that the quotient recorded in the Y' portion of the E line is recirculated and the sign of the quotient, as stored in the K5 flip-flop, is recorded in

54

the Y portion, the proposition K5 0 Y being passed by the E0 net.

The sign as set in K5 is also recorded in the Y portion of the remainder in the F line, the proposition K5 0 Y being generated by the E0 net and passed by the F0 net.

M is set true at P0 Sync time to effect advancement of the computer into state #1. P0 Sync insures that the Q register is located under the record head at state #1.

10

State #1

Upon advancement of the computer into this state, the quotient register of the A channel passes beneath the record head 103 (FIG. 3) and the quotient is recorded therein. The remainder is transferred into the E line.

The operation is as follows:

A0—E5
 A rec.—Set
 E0—F5
 F0—Recirculate
 G0—Recirculate

20

The above indicates that the output of the E line is connected to the input of the A line to record the quotient in the A channel.

25

The output of the F line containing the remainder is connected to the E line to record the remainder therein.

The lines F and G are recirculated.

30

Since M was set true in state #0, and has not been altered, the computer will automatically advance into state #2.

State #2

Upon advancement into this state, the remainder, now in the E line, will be recorded in the remainder of the A line as R is recorded in this line adjacent to Q.

35

The operation is as follows:

A0—E5
 A rec.—Set
 E0—Recirculate
 F0—Recirculate
 G0—Recirculate
 om—Pn

40

The above indicates that the output of the E line containing the remainder is connected to the input of the A line.

45

M is set to zero in preparation for state #3.

The E, F and G lines are recirculated.

PRINT ROUTINE

50

The print routine comprising states #12 to #24 is entered into from state #11 of the memory look-up routine and is effective to control the printing solenoids to properly register the amount to be read out of the computer. The proper ribbon color is selected in accordance with the particular control key depressed. Also, the symbols are selected to indicate the type of factor or result, and/or the type of operation performed.

State #12

60

Upon advancing to state #12, 1's are entered into the Y portion of the F line to subsequently enable detection of the end-of-print routine.

The black or red ribbon color selecting thyratrons is fired.

65

The operation is as follows:

E0—Recirculate
 F0—Y
 m—Set
 Black—Y[E5'($\Theta + \odot$)' + E5($\Theta + \odot$)]Z'
 Red—Y[E5'($\Theta + \odot$) + E5($\Theta + \odot$)]Z'

70

The above indicates that the value 1111 is entered into the Y portion of the F line.

75

If the Y portion of the E line containing an amount to be printed has the value 0000 registered therein, in-

dicative of positive sign, and the minus or enter-minus key has not been depressed or if Y of E contains 1111 indicative of a minus sign and the minus or enter-minus key has been depressed, the proposition

$$Y[E5'(\ominus + \odot) + E5(\ominus + \odot)]Z'$$

is passed by the "black" net of FIG. 30A. In this case, plus voltage will be applied to the ignitor of the "black" thyratron (FIG. 67) to fire the same and thereby energize the black ribbon setting solenoid 364. In case of double print on red operation, the black is inhibited at the second operation due to K.B. release.

However, if Y of E contains the value 0000 and the minus or enter-minus key has been depressed or if Y of E contains 1111 and the minus or enter-minus key has not been depressed, the proposition

$$Y[E5'(\ominus + \odot) + E5(\ominus + \odot)]Z'$$

will be passed by the red setting net of FIG. 30B, causing a plus voltage to be applied to the ignitor of the "red" thyratron to fire the same and energize the red setting solenoid 353.

M is set true by the state term 12, causing the computer to automatically advance to state #13 in case it has entered false (second time through on double print).

State #13

In this state, the first of three symbol codes is recorded in the Y portion of the F line. The format code, depending upon the setting of the format switch of FIG. 56, is entered in the Y portion of the E line.

The format switch is set to indicate the number of decimal digits, counting from the right, which will be printed on any one line.

The operation is as follows:

E0—E5 Y' + Y (Code 1) + Y (Code 2)
 F0—K4 Y' + Y (Symbol)
 G0—Recirculate
 k1—F5
 ok1—F5'
 k2—K1
 ok2—K1'
 k3—K2
 ok3—K2'
 k4—K3
 ok4—K3'
 k6—E5 Y
 ok6—E5' Y

The above indicates that the Y' portion of the E line is recirculated and that a code representing the format switch position is set in the Y portion of the E line. Such code is obtained by the format switch terminals which are connected to various net outputs indicated in FIG. 56. The following table indicates the different denominational representing positions of the code switch, the codes for such positions and the particular connection to the various net outputs.

Format switch position	Code				Connections
	P3	P2	P1	P0	
1	1	1	1	1	Plus 10 volts
2	1	1	1	0	B2' + P3
3	1	1	0	1	B1 + P3
4	1	1	0	0	P2 + P3
5	1	0	1	1	P0 + P1'
6	1	0	1	0	B1'
7	1	0	0	1	B2
8	1	0	0	0	P3
9	0	1	1	1	P0 + B2'
10	0	1	1	0	B2'
11	0	1	0	1	B1
12	0	1	0	0	P2
13	0	0	1	1	P0 + P1
14	0	0	1	0	P1
15	0	0	0	1	P0
16	0	0	0	0	Ground

The symbol code for the first symbol applied to the F line is as follows:

Symbol	Code			
	P3	P2	P1	P0
D	1	0	0	1
I	1	0	0	0
+	0	1	1	1
-	0	1	1	0
÷	0	1	0	1
×	0	1	0	0

The above code is solved by a portion of the symbol net shown in FIG. 74. The P0 pulses are obtained from a logical sum gate 520 whose output forms one input of a logical product gate 521. Thus, P0 pulses are obtained in the state #13 when any of the plus, divide or dividend keys has been depressed, the latter in the absence of depression of the plus, divide, multiply, enter-plus, enter-minus or print-only keys.

P0 pulses are obtained from the combined sum and product gate net 522. The P2 pulses are obtained from the product gate 523 and P3 pulses are obtained from the net 524.

The sign found in the Y portion of the E line is stored in K6, the latter being set true if the sign is false, and set false if the sign is true.

The F line is shifted to the left by shifting the same through the K1 to K4 flip-flops in the manner described hereinbefore.

The G line is recirculated.

Since M is still true, the computer will automatically advance to state #14.

State #14

In this state, the second of the three symbol codes is recorded in the Y portion of the F line, in a digit section directly following the first symbol code recorded therein in state #13.

The operation is as follows:

E0—Recirculate
 F0—K4 Y' + Y (Symbol)
 G0—Recirculate
 k1—F5
 ok1—F5'
 k2—K1
 ok2—K1'
 k3—K2
 ok3—K2'
 k4—K3
 ok4—K3'

From the above it will be seen that the F line is shifted to the left by shifting the same through the K1 to K4 flip-flops, and the second symbol code is inserted in the Y portion, the first symbol code having been shifted to the first digit section of the Y' portion.

The lines E and G are recirculated.

60 The symbol code for the second symbol is as follows:

Symbol	Code			
	P3	P2	P1	P0
T	0	1	1	0
S	0	1	0	1
Q	0	1	0	0
C	0	1	1	1
P	0	0	1	1
>	0	0	0	1
<+	1	0	0	0
<	1	0	0	0

The above code is solved by a portion of the symbol net shown in FIGS. 73 and 74 wherein the state term 14 is used as one of the inputs.

Since the true condition of M has not been changed, the computer will now advance to state #15.

State #15

In this state, the third symbol code is recorded in the Y portion of the F line directly following the second code which was recorded therein in state #14, and shifted into the Y' portion.

The operation is as follows:

E0—Recirculate
 F0—K4 Y'+Y (Symbol)
 G0—Recirculate
 k1—F5
 ok1—F5'
 k2—K1
 ok2—K1'
 k3—K2
 ok3—K2'
 k4—K3
 ok4—K3'

It will be noted that the computer functions the same in this state as in states #13 and #14. However, the symbol code for the third symbol is as follows:

Symbol	Code			
	P3	P2	P1	P0
A1.....	1	0	0	1
A2.....	1	0	0	0
A3.....	0	1	1	1
A4.....	0	1	1	0
A5.....	0	1	0	1
A6.....	0	1	0	0
A7.....	0	0	1	1
A8.....	0	0	1	0
A9.....	0	0	0	1

The above symbol code is solved by a portion of the symbol net shown in FIG. 73.

Since M is set true, the computer will advance to state #16.

State #16

In this state, the contents of the G line are fed into the F line to reverse the ordinal arrangement of the digits so that they will be subsequently serially entered into the pin carriage of the printer in proper order. That is, the digits which were recorded in the G line, lower-most order first, are now reversed in order upon being recorded in the F line so that they may be subsequently read out, highermost order first, along with the three symbol codes recorded in the F line in the states #13, #14 and #15.

The operation is as follows:

E0—Y'E5+Y (M E5'+M'E5)
 F0—Y G1+Y' K4
 G0—Y' G1
 k1—F5
 ok1—F5'
 k2—K1
 ok2—K1'
 k3—K2
 ok3—K2'
 k4—K3
 ok4—K3'
 k7—E5 Y
 ok7—Pn (10+16+62+76)
 m—Pn+P3 Y (Z'+K5')
 om—E5 Y (P0—P2)+K7 Y'G1 (10 key) (Z+K5')

The above indicates that the Y' portion of the F line is shifted to the left by shifting the same through K1 to K4 and the Y portion of the G line is recorded in the Y portion of the F line once per word time, thereby transferring the digits from the G line to the F line.

Since the G2 to G5 flip-flops are bypassed in recirculating the G line, the latter will be effectively shifted a direction opposite to the direction of shift of the F line to pick off the next successively higher order digits each 5 word time. Therefore, the F line will have registered therein the three symbol codes and the digital information transferred thereto from the G line in reverse order.

The format code in the Y portion of the E line is counted down once per word time using M to simulate 10 the subtrahend of 1 to establish the printing format in the same manner as the count-down operation is effected in state #10. M is set true if the G line is exhausted or if the format switch count is reduced.

K7 is set true under control of the format code in 15 the Y portion of E as long as a significant digit is left therein and is set false at Pn at the end of each word time. K7 then controls the setting of M. That is, M=1 if K7=1 and the G line is exhausted. M is set false during the Y portion of each word time 20 in which a significant digit remains in the Y portion of E or as long as digits are left in the G line.

In other words, M is set false to maintain the computer in state #16 until the format code is reduced to zeros or until only zeros remain in the particular portion 25 of the G line designated by the format switch whichever occurs sooner. However, since M is also used to count down during this state, it is set false during the P0, P1 or P2 pulse time as long as a significant digit 30 remains in the Y of E and is set true at P3 pulse time if the operation is a first print, i.e., if Z is false or if K5 is false which could occur only if a second print has occurred. Since the P3 pulse will be effective to set M only upon the beginning of the next pulse time, P0, 35 M will always be set true at the start of the Y' portion of each new word time. M will then be set false only if the G line is not exhausted and the format code is not reduced.

State #17

In this state, the computer can be arranged to skip back to the beginning of the print routine, i.e., back to state #12, if a second print is to occur. Otherwise, it will advance to state #20.

The operation is as follows:

E0—K6 Y+E5 Y'
 F0—K4 Y'
 G0—Recirculate
 k1—F5
 ok1—F5'
 k2—K1
 ok2—K1'
 k3—K2
 ok3—K2'
 k4—K3
 ok4—K3'
 ok5—Pn
 k6—Set Y'
 om—Pn+K5 Z

From the above, it will be seen that the sign initially set in K6 is reset in the Y portion of the E line and the rest of the E line is recirculated. Thereafter at Y', K6 is set true.

Since the last digit information processed in the F line in state #16 is located in the Y portion thereof, the F line is shifted to the left by shifting the same through K1 to K4 flip-flops. This is required for proper processing of digits for the print thyatrons.

If Z has been set true requiring a second print, and K5 is true indicating that this is the first time that the computer has passed through state #17, M will be set false causing the computer to return to state #12. Otherwise, 75 it will advance to state #20.

Since the P_n pulse will be effective to set K_6 false and M false, such will take place at P_0 in the next successive state #20 (or state #12 in the case of a second print).

State #20

In this state, information in the F line is recorded in the G line for subsequent print-out operation, and the feedback relay is energized.

E0—Recirculate
F0—Recirculate
G0—F5
 k_5 —Z'G5 (2nd print switch)
 m —Ten key
 om — P_n

The above indicates that the contents of the F line are directly transferred to the G line. The proposition $Z'G5 20$ (2nd print) is passed by the k_5 net of FIG. 38 to indicate that K_5 is set true if any digits are left in the G line.

M is set true by a ten key switch (not shown) which may be assumed for the purpose of the disclosure to be continuously closed. Thus, the proposition ten key 20 will be always generated by the set m net when in this state. Accordingly, the computer will automatically advance to state #21, but upon entering the same, M will be set false since it is set by the P_n pulse.

It will be noted that the state term 20 will fire a feedback relay thyatron 525 (FIG. 67) to energize a thyatron feedback relay 526. The make contacts of the latter connect a source of B plus voltage to the coil of the feedback relay 310, energizing the same to apply a "FB closed" signal to line 315 and to remove a "FB open" signal from line 314.

State #21

The computer, upon advancing to this state, is held therein until the feedback relay 310 is closed.

The operation is as follows:

E0—Recirculate
F0—Recirculate
G0—Recirculate
 m —FB closed
 om — P_n

The above indicates that the E, F and G lines are merely recirculated.

M is set true by the "FB closed" signal, the term "FB closed 21" being passed by the set m net. Since M is normally false in this state, it will be retained in such condition until the feedback relay has been closed, whereupon it will advance to state #22, being again set false at the start of this new state by the P_n pulse.

State #22

Upon advancing to this state, the computer is held until the feedback relay 310 is open.

The operation is as follows:

E0—Recirculate
F0—Recirculate
G0—Recirculate
 m —FB open

The above indicates that the E, F and G lines are recirculated.

M is set true by the "FB open" signal, the terms "FB open 22" being passed by the set m net to cause the computer to advance to state #23. The FB relay 310 (FIG. 67) is opened by positive action of the pin carriage.

State #23

Upon advancement to this state, a selected print thyatron, i.e. 304 (FIG. 67), is fired in accordance with the first digit read-out of the G line.

The operation is as follows:

E0—Recirculate
F0—Recirculate
G0—G1 Y'
 k_1 —G1 Y
 ok_1 —G1'Y
 k_2 —K1 Y
 ok_2 —K1'Y
 k_3 —K2 Y
 ok_3 —K2'Y
 k_4 —K3 Y
 ok_4 —K3'Y
 om —G1 Y'

15 The above indicates that the G_1 to G_5 flip-flops are bypassed in recirculating the Y' portion of the G line, thereby shifting the G line to the right one digit section per word time.

Also, during each word time, the Y portion of G containing the next digit to be read is shifted into the K_1 to K_4 flip-flops.

M is set false by the proposition $G_1 Y'$ and will be held in such condition as long as a marker remains in the G lines, causing the computer to skip back to state #21 and thereby successively transfer the digits in the Y' portion of the G line into the Y portion where they are shifted into K_1 to K_4 to fire the thyatrons corresponding to the next succeeding digits until all digits are processed.

It will be recalled that as each thyatron is fired, the corresponding solenoid 251 (FIG. 67) is energized by setting a corresponding stop pin in the pin carriage of the printer so as to successively set up all digits of the amount to be printed into the pin carriage, including three symbols.

When all digits are removed from the G line, M , being set true in state #22, will remain true through state #23, causing the computer to automatically advance to state #24.

State #24

Upon advancing to this state, the printer is operated to record or print the digital and symbol information now set up on the pin carriage.

The operation is as follows:

E0—Recirculate
F0—Recirculate
G0—Recirculate
 om — P_n

50 The above indicates that the E, F and G lines are recirculated.

The state term 24 is applied to the ignitor of the print thyatron 320 (FIG. 67) to energize the print relay 311 and thereby cause operation of the printer as was described heretofore.

55 Since M remains true upon advancing to this state, the computer will automatically advance to state #25.

However, if K_5 has been set true in state #20 indicating that the second print operation is to follow, the proposition $P_0 Y K_5 24$ will be passed by the set z net of FIG. 29 to set Z true to cause a second print. Otherwise, Z will remain false.

PROGRAM CONTROL UNIT

65 A program unit is provided to repetitively control operation of the machine to perform preset programs of operation in lieu of manual control by the keyboard.

Two alternative forms of presettable program controls are provided. One such control comprises a plug board, generally indicated at 600 (FIG. 76). The latter comprises two main groups of hubs. One main group comprises function control hubs connected to different function control terminals in the machine, and the other comprises program step control hubs connected to different contacts of a multi-level stepping switch.

61

Flexible plug connectors are suitably connected between selected function control hubs and selected program step control hubs to determine the particular functions and order of operations to be performed by the machine during the different steps of the machine. The program may be changed as desired by changing the setting of the different plug connectors.

The other program control comprises a prewired multi-plug unit, generally indicated at 599, which is plugged into a multi-socket unit. Certain sockets or hubs of the latter are wired to different function control terminals in the machine and others are connected to certain terminals of the step switch. The plug unit, when plugged into the socket unit, connects different step switch contacts with preselected function control terminals in the machine so as to operate in the same manner as the plug board unit. However, the plug unit may be readily replaced by another plug unit which has been prewired to produce a different program of operations of the machine.

Referring to FIG. 76, the plug board 600 is divided into different hub sections, each including a group of hubs. One section 601 includes a plurality of horizontal rows of six hubs each, the hubs in each row being connected together and to the make contact of the correspondingly identified control key switch so as to generate the same single identified terms as are generated by the associated control keys. For example, the row identified as Q (quotient) is connected by a line 602 (see also FIGS. 58 and 78) to the make contacts of the switch operated by the quotient key 13. Likewise, the R (remainder) row of hubs is connected by line 603 to the make contacts of the switch operated by the remainder key 33. Remaining hubs are similarly connected to the make contacts or switches associated with the correspondingly identified control keys.

A function control hub section 604 selects the various storage accumulators and for this purpose each horizontal row of hubs is arranged to select a correspondingly identified storage accumulator. The hubs of each horizontal row are connected together and to the make contacts of the switch controlled by the correspondingly identified accumulator selection key. For example, the hub for selecting the A1 accumulator is connected by line 605 (FIGS. 57 and 78) to the make contact of the switch operated by the A1 selection key. The remaining hubs are similarly connected.

The non-print hubs located in section 606 of the plug board are connected by a line 607 to the transfer contact of the non-print switch lever 39 (FIG. 59). The master clear hubs of section 606 are connected by a line 608 to the make contact of the switch associated with the master clear switch 45 (FIG. 58).

The hubs of digit section 610 are connected to the make contacts of the switches of a correspondingly identified digit key in FIG. 57. For example, the zero digit hubs are connected by line 611 to the make contact of the switch of the zero key. The hubs of the decimal point (DP) section 612 are connected to the make contacts of the correspondingly identified terminals of the decimal point switch in FIG. 54. For example, the DP1 hubs are connected by a line 613 to the correspondingly identified make terminal of the decimal point switch (FIG. 54).

The aforementioned function control hubs are arranged to be connected by flexible plug connectors, i.e. 614, to different ones of a plurality of hubs located in a program step control hub section 615. The latter are connected to correspondingly identified contacts of a step switch, generally indicated at 616 (see FIGS. 81 and 82). When the step switch advances through a cycle of operation, a relatively high voltage is successively applied to consecutively higher valued horizontal rows of the hubs in section 615 to control the operation of the machine in accordance with the placement of the plug connectors.

62

STEP SWITCH

The step switch 616 (FIGS. 81 and 82), in general, comprises a base 621 to which are secured bearing brackets, i.e. 622. The latter form bearings in which a rotor 623 is rotatably mounted. The latter supports two longitudinally extending plates 624 of insulating material on opposite sides thereof, to which are secured sets of flexible bridging brushes 625, one set for each bank or level of the switch. The brushes in each set are located 180° apart and are arranged to wipe over thirty sets of contacts, i.e. 626. Each set of contacts is adapted to be bridged by one of the brushes for the corresponding level at a particular point in the switch cycle.

15 The contacts 626 are embedded in a cylinder 627 of insulating material suitably secured to the base 621.

Means are provided for advancing the rotor in a step by step fashion to advance the brushes 625 from bridging contact with one set of contacts into bridging contact with the next succeeding set. For this purpose, the rotor has 20 attached thereto a ratchet wheel 628 which is advanced by a pawl 630. The latter is supported by a leaf spring 631 mounted on a pawl arm 632. The latter is pivoted at 633 to a part of an electromagnet frame 634 suitably attached to the base 621. A stepping coil 635 is carried 25 by the frame 634 and cooperates with an armature 636 forming part of the pawl arm 632. The coil is effective, when energized, to rock the pawl arm counterclockwise against the action of a tension spring 637 so as to move the pawl 630 from engagement with one ratchet tooth 30 into engagement with a next succeeding tooth.

When the magnet coil is deenergized, the spring 637 is effective to rock the pawl arm to cause the pawl to advance the rotor one step in a clockwise direction.

35 A group of "home" contacts are provided comprising a set of normally open contacts 638 and a set of Class C contacts forming normally closed contacts 639 and normally open contacts 640. The blades for the various contacts are supported by blocks 641 of insulating material supported by the base 621. The contacts are controlled 40 by a double lobed cam 642 attached to the rotor, and effective to wipe over a flexible contact control blade 642a which is connected to certain only of the home contact blades by insulating pieces 642b.

45 Also included in the step switch is a set of normally closed "commutator" contacts 643. One of the latter is supported by a relatively stiff blade 644 and the other by a flexible spring blade 644a having a camming portion 645 engageable by a projection on a slide 646 of insulating material. The slide is pivotally connected at 647 to an extension of the pawl arm 632. When the magnet coil 635 is energized, the slide 646 is moved to the left in FIG. 81 by the pawl arm 632 to cam the spring blade 644a outwardly to break the contacts 643. However, the initial impulse applied to the magnet is sufficient to 50 throw the pawl completely from one tooth to the next, even though contacts 642 break, so that the spring 637 will be effective to return the same and thus advance the rotor.

PROGRAM UNIT CIRCUIT

60 The various banks or levels of the stepping switch are shown in developed form in FIG. 77 and are identified at A, B, C, D, E and F.

The contacts of the different step switch levels are arranged in two groups, one identified as group I and the other as group II. The contacts are numbered from H to 15 in group I and 16 to 30 in group II. A brush 625 in each level will bridge the sets of brushes H and 65 16 when the switch is in home position (as indicated in FIG. 77).

70 It will be noted that in levels A to E, inclusive, the upper contacts of each group are connected in common whereas the lower contacts of each group are connected to individual lines grouped in trunks.

The common lines of groups AII, EII and EIII are con-

ected to the lower contacts of part of a double throw switch 616 which is manually settable into either of two positions. The latter switch, when set into its illustrated position, renders the plug board effective to control programming of the machine and when set into its alternate position, renders the prewired program plug unit 599 effective to control programming. In its illustrated position, the switch 616 connects a source 650 of plus 10 volts to the transfer contacts of a relay 651.

The upper contacts of the step switch contact groups BII, CII and DII are connected to the break contacts of a normally deenergized relay 651. 10

The upper contacts of the switch groups BI, CI and DI are connected to the make contacts of the relay 651.

The upper contacts of the step switch group AI are connected in common through a resistor to a source of plus 150 volts while the lower contacts of this group are connected through individual lines to the upper terminals of respective ones of a series of neon indicator lamps 653, the lower terminals of which are connected to a plus 4 volt supply line. Accordingly, successive ones of the lamps 653 are illuminated as the step switch advances through its different steps in its cycle.

The lower contacts of the step switch groups AII, EII and EI are connected through trunks 654, 655, and 656, respectively, to the hubs of a prewired program socket unit, generally indicated at 657 (FIG. 79), to be described later.

The lower contacts of the step switch groups BI, BII, CI, CII, DI and DII are connected through trunks, like trunk 658 to the correspondingly identified hubs in the program step hub section 615. That is, there is one hub for each of the step switch contacts in the groups BI, BII, CI, CII, DI and DII.

Normally, in the absence of insertion of a plug connector in the hubs marked 15 or 30 in the hub section 660, the step switch will automatically advance through 15 steps to successively energize the hubs in the vertical rows identified as BI, CII and DII in the step hub section 615, since in such condition, the relay 651 is deenergized and the 10 volt potential from source 650 will be applied only to the step switch contact groups BII, CII and DII. However, if a plug connector were to be bridged over the hubs marked "15" in the hub section 660, it would, through lines 661, connect the common lines of groups BI and BII together. Accordingly, the hubs of group BI would be energized in sequence along with the hubs of the previous three rows.

When a plug connector is bridged across the hubs marked "30" of section 660, a double cycle of operation of the step switch is effective, causing the first three vertical rows of hubs DII, CII and BII of the program step section 615 to be first successively scanned or energized during the first fifteen steps or cycle of the step switch, and thereafter the next three vertical rows BI, CI and DI to be so energized. For this purpose, the lower hub of the pair marked "30" is connected in series with a diode 662 and a coil of a "30 step" relay 663 to ground. Holding contacts 664 are connected to a source of plus 30 volts. The step switch contacts FIH are connected by lines 665 across the coil of relay 663 so as to short the latter out when the step switch is in its home position wherein the brush 625 bridges the latter contacts. It should be noted at this point that only one bridging brush (625a) is provided for level F and that most of the contacts in level F are dead.

The upper hub of the pair marked "30" is connected through line 666, contacts 667 of the settable switch 616, line 668 and step switch contacts FI 15 to terminal SW30. The latter terminal (see FIGS. 67 and 78) is connected through contacts 1670 of a normally energized relay 671 and contacts 672 of the aforementioned relay 325 to a plus 30 volt supply.

The coil of relay 671 is connected at its lower end to the plus 10 volt line 1325 and at its upper end through a

line 673 and contacts 674 of relay 325 to a 150 volt B plus supply so as to normally maintain the relay 671 energized concurrently with energization of the relay 325 as an incident to depression of certain of the function control keys, as described heretofore.

A thyratron type tube 675 has its cathode and anode connected across the coil of relay 671 and is normally biased in a normally conducting condition. Accordingly, upon operation of the machine and energization of relay 325, a 30 volt potential will be applied to the terminal SW30, and if a plug connector is plugged in the hubs marked "30," the "30 step" relay 663 will be energized as the step switch reaches step 15 wherein brush 625a will bridge the contacts FI 15.

Contacts 670 (FIG. 77) of relay 663 are located in the energizing circuit of relay 651. Therefore, when the relay 663 is energized, the relay 651 will also become energized to apply plus 10 volts from the supply 650, through switch 616 to the upper contacts of the step switch groups BI, CI and DI. Accordingly, as a second cycle of the step switch ensues (as will be described later), the hubs of the vertical rows indicated at BI, CI and DI of the program step switch section 615 will be successively energized.

As the step switch reaches home position of the second cycle, the sole brush 625a in bank F will return to bridge the contacts FIH, thereby shorting out the relay 663, allowing its locking contacts 664 to open to stop the step switch.

Describing now the means for initiating and controlling operation of the step switch, the stepping magnet 635 of the latter (see FIG. 77) is connected in series with a minus 30 volts supply, home contacts 639 of the step switch, a "program start" switch 675 and "commutator" contacts 642 of the step switch to a source of plus 30 volt supply. Accordingly (assuming the settable switch 616 to be in its illustrated position rendering the plug board effective to control programming of the machine, and the plug connectors in place to effect the programming), when the "program start" switch 675 is closed, the magnet 635 will be effective to advance the step switch to its No. 2 position, thereby closing the home contacts 638 and 640 (see also FIG. 78), and opening contacts 639.

Upon advancing to its No. 2 position, the No. 2 horizontal row of the program step hubs will be energized and the machine will be operated to perform a particular function depending upon the placement of the plug connector or connectors plugged into this horizontal row of hubs. Accordingly, upon operation of the machine and consequent energization of terminal SW30, a circuit will be completed from SW30 (see FIG. 77), line 676, home contacts 640 and stepping coil 635 to advance the step switch to its next No. 3 position. This procedure will be repeated as the step switch advances and the machine is operated in response thereto, providing plug connectors are bridged between at least one hub of the successive horizontal rows of the program step section and any of the machine function control hubs.

When the step switch advances to a position corresponding to a horizontal row of holes in the program step section in which no plug connector is plugged, the step switch will come to rest. The machine may thereafter be operated under control of the keyboard in the usual manner in which event the step switch will advance one step toward its home position during each such operation.

Should a plug connector be bridged between a hub in the program step section and a hub marked "skip" (FIGS. 76 and 78), advancement of the step switch to the correspondingly identified position will apply a plus 10 volt from supply source 650 through the plug connector, line 677, coil of a "skip" relay 678, the now closed home contacts 638 to a source of plus 30 volts, thereby energizing the relay 678. Locking contacts 680 connected in circuit with a plus 10 volt supply will thereafter hold the skip

relay closed until the step switch advances to its home position, wherein the home contact 638 will open. Upon energization of relay 678, contacts 681 (FIG. 77) thereof are closed to complete a circuit from the plus 30 volt supply, through commutator switch 642 and home contacts 640 to the step switch coil 635 permitting the same to automatically advance the step switch repetitively until it reaches home.

Describing now the means for maintaining the step switch in operation through successive cycles in the event that the hubs marked "30" in section 660 are bridged, it will be noted in FIG. 77 that the home contacts 640 are shunted by a circuit comprising contacts 683 of the "30" count relay 663 and step contacts FII 16. Therefore, and assuming that the "39" hubs are bridged; when the step switch reaches the end of its first cycle, relay 663 will be energized as described heretofore, and contacts 683 will be closed. As the step switch advances to position 16, the step magnet circuit will be completed from the source SW30 through contacts FII 16, through contacts 683 and stepping magnet 635 of the step switch.

Describing now the prewired program plug arrangement of FIGS. 79 and 80, the latter comprises a plurality of sixteen horizontal rows of hubs corresponding in number to the sixteen steps of the step switch. The outer hubs of the different rows are connected to different control function terminals in the same manner as the function control hubs of the plug board section and as indicated. For example, the function control hub 684 is connected by line 602a to make contact of the dividend key operated switch (FIG. 59). Likewise, the hub 685 is connected through the line 605a to the make contact of the switch operated by the A1 selection key of FIG. 57. The central three hubs of the various horizontal rows are connected as mentioned heretofore by individual wires to the corresponding lower contacts of the step switch groups AII, EI and EII.

The plug unit, generally indicated at 636 (FIG. 80), comprises a plurality of rows of plugs 687 insulated from each other and adapted to be inserted in corresponding ones of the hubs of FIG. 79. Electrical conductors 688 are wired between the inner and outer plugs 686 in accordance with a preselected program. When the plug unit is inserted in the hub section 657, and the switch 616 is thrown to its alternate "program plug" position, plus 10 volts will be supplied from source 650 to the upper contacts of the stepping switch groups AII, EI and EII. Therefore, when the step switch is advanced from its home position by depression of the program start button 675, the program unit will perform in the same manner as under control of the plug board unit.

An automatic program start device is provided to automatically start operation of the program control device only upon depression of a certain function control key. For example, it may be desired to control the machine by the usual keyboard control keys to perform certain calculations and to cause an automatic program of operations to occur as an incident to depression of the total key 20.

For this purpose, an automatic start relay 690 (FIG. 78) is provided, the coil of the latter being connected in circuit with a source of 30 volt, through lines 689 to contacts EII 16 of the step switch, and line 691 to a group of hubs 692 located in the hub section 660. Contacts 693 (FIG. 77) of the relay 690, are located in series with the aforementioned terminal SW30 and the home contacts 639 of the step switch. Accordingly, when a plug connector is bridged between one of the automatic start hubs 692 and a selected function control hub, depression of the correspondingly identified function control key will complete a circuit through the auto-start relay 690 to energize the stepping relay coil 635 and thus advance the step switch from its home position. The step switch will then automatically advance from its home position to control functioning of the machine in the same man-

ner as previously described and under control of either the plug board control unit or the program plug unit depending upon the setting of the switch 616.

In order to more clearly understand the operation of the program control unit, an example of a progressive discount problem will be considered.

Assume, for example, that it is required to find the results of successive discounts of 24%, 16% and 8% of different values for tax assessment purposes.

The accumulator controls are set as follows. The switch lever 38 is thrown into position to cause all totals to be accumulated in accumulator A1. The value 24 is entered negatively into accumulator A4 by entering the value in the keyboard and depressing the enter-minus key 35. Likewise, the values 16 and 8 are entered negatively into the A5 and A6 accumulators, respectively.

Considering the above entry, the operation of the machine to perform the calculation can be symbolically tabulated as follows:

Step:	Function
(1)	Program Start Switch closed,
(2)	A1<+.
(3)	A1>1.
(4)	A4>X.
(5)	T.
(6)	A1>1.
(7)	A5>X.
(8)	T.
(9)	A1>1.
(10)	A6>X.
(11)	T.
(12)	A1 C.
(13)	Skip.

Plug connectors are inserted in the plug board as indicated by the heavy dotted lines in FIG. 78.

Plug connectors 696 and 697 are inserted at one of each thereof in the leftmost hubs of the No. 2 row in section 615 and their other ends are inserted in the hubs of the rows identified as A1 and the reset symbol > in sections 606 and 601, respectively, thereby satisfying the terms of the second step. Other plug connectors are plugged in the hubs of other rows in a similar manner in accordance with the above table to control functioning of the machine accordingly. As only twelve steps of the step switch are necessary in this program, a plug connector is connected between a hub in row No. 13 of section 615 and a hub in the "skip" row 615a to cause the step switch to skip or advance on to home position.

Since only the A1 accumulator is cleared during the last operation of the machine, corresponding to step No. 12 of the switch, the machine will be in condition for receiving the next value to be operated on.

Although we have described our invention in detail in its preferred form and have therefore utilized certain specific terms and languages herein, it is to be understood that the present disclosure is illustrative rather than restrictive and that changes and modifications may be made without departing from the spirit or scope of the claims appended hereto.

Having thus described the invention, what we desire to secure by United States Letters Patent is:

1. In an electronic calculating apparatus, an adding device comprising the combination of means for separately registering two numbers to be added, means for comparing the algebraic signs of said numbers, means controlled by said comparing means when said signs are the same for adding the value 6 to each digit of one of said numbers to obtain a first sum, means for adding the other of said numbers to said first sum to obtain a second sum, means for determining the smaller of said numbers, means controlled by said comparing means and by said last mentioned means when said signs are different for complementing the smaller of said numbers and for add-

ing said complemented number to the other of said numbers to obtain an alternate second sum, means controlled by said last mentioned means when said signs are different for adding the fugitive one to said alternate second sum, and means for adding the value 10 to each denomination of said second sum in which a tens carry does not occur to obtain the algebraic sum of said numbers, said last mentioned means being ineffective to cause tens carries.

2. In an electronic calculating apparatus, an adding device comprising the combination of a magnetic record member having first and second magnetic tracks therealong for registering two numbers, respectively to be added, a first read head and a first record head associated with said first track and spaced from each other, a second read head and a second record head associated with said second track and spaced from each other, means for comparing the algebraic signs of said numbers, means controlled by said comparing means when said signs are the same for adding the value 6 to each digit of one of said numbers read by said first read head and for causing said first record head to record the sum thereof, means including said first read head and said second read head for adding said recorded sum to said other number to obtain a second sum and for causing said first record head to record said last mentioned sum, means for determining the smaller of said numbers, means controlled by said last mentioned means and by said comparing means when said signs are different for complementing the smaller of said numbers and for adding said complemented number to the other of said numbers to obtain an alternate second sum, means controlled by said last mentioned means when said signs are different for adding the fugitive one to said alternate second sum, means for causing said first record head to record the sum thereof, means for adding the value 10 to each denomination of said second sum recorded by said first record head in which a tens carry does not occur to obtain a third sum, said last mentioned means being ineffective to cause tens carries, and means comprising said second record head for recording said third sum on said second track.

3. In an electronic calculating apparatus, the combination comprising arithmetic instrumentalities, a multi-denominational register for registering results of calculations performed by said arithmetic instrumentalities, a cyclically operable multi-denominational gang printer for simultaneously printing a multi-denominational number, said printer having a smaller denominational capacity than said register, means operable as an incident to registration of a value by said register for causing a cycle of operation of said printer, and means responsive to registration of a value in said register which is greater than the capacity of said printer for causing a second cycle of operation of said printer to print a portion of said value not printed during said first cycle.

4. In an electronic calculating apparatus, the combination comprising arithmetic instrumentalities, a multi-denominational register for registering results of calculations performed by said arithmetic instrumentalities, means comprising a printer for printing values registered by said register, said printer having a capacity to print fewer denominations than the capacity of said register, means operable as an incident to registration of a value by said register for causing an operation of said printer to print out a certain number of denominations registered by said register, and means responsive to registration of a value in said register which is greater than said capacity of said printer for causing a second operation of said printer to print a portion of said denominations registered by said register and not printed during said first mentioned operation.

5. In an electronic calculating apparatus, the combination comprising arithmetic instrumentalities, a multi-denominational register for registering results of calculations performed by said arithmetic instrumentalities, means comprising a printer for printing values registered

by said register, means for selectively predetermining the capacity of said printer to print different numbers of denominations fewer than the capacity of said register, means operable as an incident to registration of a value

5 in said register for causing operation of said printer to print a number of said denominations registered by said register up to said capacity predetermined by said second mentioned means, and means responsive to registration of a value in said register which is greater than the capacity predetermined by said second mentioned means for causing a second operation of said printer to print a portion of said denominations registered by said register and not printed during said first mentioned operation of said printer.

10 6. In an electronic calculating apparatus, the combination comprising arithmetic instrumentalities, a multi-denominational register for registering results of calculations performed by said arithmetic instrumentalities, a cyclically operable multi-denominational gang printer for simultaneously printing a multi-denomination number, means for selectively predetermining the capacity of said printer to print a number of denominations fewer than the capacity of said register, means operable as an incident to registration of a value by said register for causing a cycle of operation of said printer, and means responsive to registration of a value in said register which is greater than the number of denominations predetermined by said second mentioned means for causing a second cycle of operation of said printer to print a portion of said 15 value not printed during said first mentioned cycle.

20 7. In an electronic calculating apparatus, the combination comprising arithmetic instrumentalities, a multi-denominational register for registering results of calculations performed by said arithmetic instrumentalities, a 25 printer for printing a multi-denominational number, said printer having a smaller denominational capacity than said register, means operable as an incident to registration of a value by said register for causing an operation of said printer, means responsive to registration of a value 30 by said register which is greater than the capacity of said printer for causing a second operation of said printer to print a portion of said value not printed during said first mentioned operation, and means for selectively rendering said last mentioned means ineffective.

35 8. In an electronic calculating apparatus, the combination comprising means including depressible amount keys for registering values, arithmetic instrumentalities, means comprising a depressible control key for said arithmetic instrumentalities; a storage register, means responsive to operation of said arithmetic instrumentalities for registering each result of a calculation in said storage register, and means responsive to depression of said control key for normally entering a value registered by said first mentioned means in said arithmetic instrumentalities, said last 40 mentioned means being responsive to depression of said control key in the absence of values registered by said first mentioned means for entering a value registered by said storage register in said arithmetic instrumentalities.

45 9. In an electronic calculating apparatus, the combination comprising means including depressible amount keys for registering values; arithmetic instrumentalities, means comprising a plurality of depressible control keys for said arithmetic instrumentalities; each of said control keys being effective to cause said arithmetic instrumentalities to perform a different function, a storage register, means responsive to operation of said arithmetic instrumentalities for registering each result of a calculation in said storage register, and means responsive to depression of any of said control keys for normally entering a value registered by said first mentioned means in said arithmetic instrumentalities, said last mentioned means being responsive to depression of said control keys in the absence of values registered in said first mentioned means for entering a value registered by said storage register in said arithmetic instrumentalities.

10. In a calculating apparatus, an adding device comprising the combination of means for separately registering two binary coded decimal numbers to be added, means for comparing the algebraic signs of said numbers, means controlled by said comparing means when said signs are the same for adding the value 0110 to each digit of one of said numbers to obtain a first sum, means for adding the other of said numbers to said first sum to obtain a second sum, means for determining the smaller of said numbers, means controlled by said last mentioned means and by said comparing means when said signs are different for complementing the smaller of said numbers and for adding said complemented number to the other of said numbers to obtain an alternate second sum and for adding 0001 to the lowermost denomination of said alternate second sum, and means for adding the value 1010 to each denomination of said second sum in which a carry does not occur to obtain an algebraic sum of said numbers, said last mentioned means being ineffective to cause tens carries.

11. In an electronic calculating apparatus, an adding device comprising the combination of a magnetic record member having first and second magnetic tracks therealong for registering two binary coded decimal numbers, respectively, to be added, a first read head and a first record head associated with said first track and spaced from each other, a second read head and a second record head associated with said second track and spaced from each other, means for comparing the algebraic signs of said numbers, means controlled by said comparing means when said signs are the same for adding the value 0110 to each decimal denomination of one of said numbers read by said first read head and for causing said first record head to record the sum thereof, means including said first read head and said second read head for adding said recorded sum to said other number to obtain a second sum and for causing said first record head to record said last mentioned sum; means for determining the smaller of said numbers, means controlled by said last mentioned means and by said comparing means when said signs are different for complementing the smaller of said numbers and for adding said complemented number to the other of said numbers to obtain an alternate second sum, means controlled by said last mentioned means when said signs are different to add 0001 to the lowermost decimal denomination of said second sum and to cause said first record head to record the sum thereof, means for adding the value 1010 to each decimal denomination of said last mentioned sum recorded by said first record head in which a tens carry does not occur to obtain a third sum, and means comprising said second record head for recording said third sum on said second track.

12. In an electronic calculating apparatus, an adding device comprising the combination of a magnetic record member having first and second magnetic tracks therealong for registering two binary coded decimal numbers, respectively, to be added, a first read head and a first record head associated with said first track and spaced from each other, a second read head and a second record head associated with said second track and spaced from each other, said drum having a third magnetic track thereon including regularly spaced pulse marks, a third read head associated with said third track, a pulse counter controlled by said third read head and effective to count said pulse marks in reoccurring groups, said pulse counter being effective to successively register the values 0110 and 1010, means for comparing the algebraic signs of said numbers, means controlled by said comparing means when said signs are the same for deriving the value 0110 from said pulse counter and for adding said value 0110 to each decimal denomination of one of said numbers read by said first read head and for causing said first record head to record the sum thereof, means including said first read head and said second read head for adding said recorded sum to said other number to 75

obtain a second sum and for causing said first record head to record said last mentioned sum; means for determining the smaller of said numbers, means controlled by said last mentioned means and by said comparing means when said signs are different for complementing the smaller of said numbers and for adding said complemented number to the other of said numbers to obtain an alternate second sum, said last mentioned means being effective to add the value 0001 to the lowermost decimal denomination of said alternate second sum and for causing said first record head to record the sum thereof, means for deriving the value 1010 from said pulse counter and for adding said value 1010 to each decimal denomination of said sum recorded by said first record head in which a decimal carry does not occur to obtain a third sum, and means comprising said second record head for recording said third sum on said second track.

13. In an electronic calculating apparatus, the combination comprising a magnetic drum having a clock track therearound including regularly spaced clock pulse marks; said drum having a sync track therearound including regularly spaced sync marks defining word portions and position pulse marks spaced intermediate certain of said sync pulse marks; a first read head controlled by said clock pulse marks, a second read head controlled by said sync marks and said position pulse marks, a pulse counter controlled by said first head, a first flip-flop circuit controlled by said second head, a second flip-flop circuit insensitive to changes in said first flip-flop circuit in response to said position pulse marks, and means controlled jointly by said first and second flip-flop circuits for inhibiting operation of said pulse counter until a predetermined relative condition of said two flip-flop circuits is reached defining a predetermined position of one of said word positions relative to said second read head and irrespective of the location of said position pulse marks.

14. The combination according to claim 13 comprising means responsive to a predetermined relative condition of said two flip-flop circuits and said pulse counter for indicating a specific point on said drum.

15. In an electronic calculating apparatus, the combination comprising a magnetic drum having a clock track therearound including regularly spaced clock pulse marks; said drum having a sync track therearound including regularly spaced sync marks defining word portions and a plurality of position pulse marks spaced intermediate said sync pulse marks; said first read head controlled by said clock pulse marks, a second read head controlled by said sync marks and said position pulse marks, a pulse counter controlled by said first head, a first flip-flop circuit controlled by said second head, a second flip-flop circuit controlled by said first flip-flop circuit, means rendering said second flip-flop circuit insensitive to changes in said first flip-flop circuit in response to said position pulse marks, means controlled jointly by said first and second flip-flop circuits for inhibiting operation of said pulse counter until a predetermined relative condition of said two flip-flop circuits is reached defining a predetermined position of one of said word positions relative to said second read head and irrespective to the location of said position pulse marks, and means responsive to predetermined relative conditions of said two flip-flop circuits and said pulse counter for indicating said position pulse marks.
